AUTOMATED LANE-DIVIDER BUTTON APPLYING MACHINE

BACKGROUND OF THE INVENTION

The invention relates to highway construction and repair machines, and more particularly to a self-propelled, fully automated machine for applying lane-divider buttons along lane-divider lines defining highway traffic lanes.

Lane-divider lines normally are employed in highway systems to define paths of travel for motorized vehicles. It has been the practice to delineate the lanes using lane-divider lines formed by applying parallel stripes or lines of paint of particular colors, which for recognition purposes, are of colors contrasting with the colors of the highway surfaces in order that lanes are clearly and readily discernible for aiding vehicle operators in maintaining vehicle control. However, the painted lines are not entirely satisfactory as they do not effectively obviate "wandering" such as that resulting from operator inattention or obscuration of the markings.

Numerous schemes have been devised, with varying degrees of success, for advising vehicle operators when vehicles "wander" from a delineated highway lane. One of the more practical recent innovations has been to define the highway lanes by applying readily apparent "strings" of lane-divider buttons along the surface of the highways.

In practice, a combination of two types of buttons are employed in defining the lanes. The first being circular and fabricated from ceramic materials, normally white in color, each having a diameter substantially equal to the width of a common lane-divider line, and so configured as to have a planar supporting surface and a domed upper surface. The second type is rectangular, preferably square, having a least one substantially vertical planar reflecting side surface and a width equal to the diameter of the circular buttons. Preferably, the circular buttons are strung in strings of four, on 3-foot centers, with the strings being spaced at 15-foot intervals to define lane-divider lines readily visible to vehicle operators. Midway between alternate strings of four circular buttons there are arranged the second type of buttons, each having its reflecting surface directed towards the oncoming traffic. Hence, the reflector surfaces of the rectangular buttons are interspersed with the strings of white buttons so that under conditions of poor visibility light from the head lamps of approaching vehicles may be gathered and directed back toward the operators for aiding the operators in visually observing the divider lines. Furthermore, in executing lane changes, vehicle operators necessarily "feel" the buttons as the wheels of the vehicle pass thereover so that the vehicle's position relative to the selected lane is determined by "feel" as well as by visual observation.

Use of these buttons, while effective, has been severely limited since heretofore it has been the practice to apply the buttons by hand. In manual applications, each of the areas which is to receive a button is first cleaned, through brushing or sand blasting operations to thereby enhance the button adhering characteristics of the surface, a "glob" of a convenient adhesive, such as epoxy, next is applied to the cleaned surface area and a selected button manually is deposited and seated in the glob of adhesive. As can readily be appreciated, manual application of the buttons proves to be excessively time-consuming and, in some instances economically prohibitive, even though the buttons have been quite effective in achieving a reduction of highway accidents.

SUMMARY AND OBJECTS OF THE INVENTION

This invention overcomes the aforementioned disadvantage in the use of lane-divider buttons by providing an economic fully automated, self-propelled machine for cleaning selected areas of the button receiving surface of the highway, depositing selected quantities of adhesive in the selected and cleaned areas and subsequently applying and seating lane-divider buttons in the deposited adhesive.

Accordingly, an object of the instant invention is to provide an automated lane-divider button applying machine.

Another object is to provide a lane-divider button applying machine particularly suited for use in applying divider buttons at selected intervals along lane-divider lines of surfaced highways.

Another object is to provide an automated lane-divider button applying machine adapted to be driven along surfaces of highways for depositing lane-divider buttons at preselected intervals in an adhesive which is applied substantially simultaneously therewith.

Another object is to provide a self-propelled and automated lane-divider button applying machine adapted to be propelled and steered along lane-divider lines of surfaced highways for cleaning selected areas of the surfaces of the highway, mixing and depositing an adhesive in cleaned areas, depositing lane-divider buttons in the applied adhesive and positively seating the deposited buttons.

Another object is to provide an automated self-propelled and steerable lane-divider button applying machine adapted to be propelled and steered along a lane-divider for cleaning selected surface areas at predetermined intervals, applying an adhesive at the cleaned areas, applying highway buttons of alternate configurations within the applied adhesive and seating the applied buttons.

Another object is to provide in a lane-divider button applying machine a button magazine adapted sequentially to deliver the buttons in series and at predetermined intervals to be deposited in applied adhesive.

Another object of the instant invention is to provide in an automated lane-divider button applying machine means for orienting the buttons as they are delivered to be applied by the machine.

Another object is to provide for an automated lane-divider button applying machine and adhesive applicator particularly suited for use in depositing globs of adhesive at preselected intervals along the surface of the highway.

Another object is to provide for an automated lane-divider button applying machine and a button ejector adapted to deliver buttons from the machine to a button receiving surface at selected intervals.

Another object of the instant invention is to provide for a lane-divider button applying machine a surface cleaning mechanism adapted to clean selected areas of the highway at predetermined intervals as the machine is advanced therewith.

Another object is to provide for a lane-divider button applying machine a guide boom connected with the surface cleaning apparatus for dictating the machine's direction of travel and the lateral displacement imposed on the machine's cleaning mechanism as the machine is advanced along the surface of a highway.

Another object is to provide a timing mechanism for sequentially controlling the simultaneously performed operations of a lane-divider button applying machine, whereby the button applying machine is caused to clean the surface of the highway, at varied intervals, deposit adhesive thereon and selectively deposit selected lane-divider buttons within the applied adhesive.

These together with other objects and advantages will become more readily apparent by reference to the following description in light of the accompanying drawings.

BRIEF DESCRIPTION OF THE DRAWINGS

FIG. 1 is a side view of the automated lane-divider button applying machine embodying the principles of the present invention.

FIG. 2 is a diagrammatic view of a preferred arrangement for strings of lane-divider buttons applied by the machine of FIG. 1.

FIG. 3 is a plan view of the machine of FIG. 1.

FIG. 4 is a fragmentary plan view, on an enlarged scale, of the adhesive and button delivery and gated track portion of the machine illustrated in FIG. 3.

FIG. 5 is a fragmentary side view of the portion of the button applying machine illustrated in FIG. 4.

FIG. 6 is a cross section taken generally on line 6-6 of FIG. 5.

FIG. 7 is a partially sectioned end view taken generally on line 7-7 of FIG. 5.

FIG. 8 is a partially sectioned side view of the gated track, illustrating the gating, adhesive applying and button ejecting mechanisms of FIGS. 4 and 5.

FIG. 9 is a cross section taken generally along the line 9-9 of FIG. 8.

FIG. 10 is a cross section taken generally along line 10-10 of FIG. 8.

FIG. 11 is a top plan view illustrating the button gating and the button ejecting mechanism shown in FIG. 8.

FIG. 12 is an inverted plan view, on an enlarged scale, of the button ejector and adhesive applicator mechanism of FIG. 11.

FIG. 13 is a partially sectioned side view of a portion of the adhesive applying, button ejecting and sequence timing mechanism, particularly illustrated in FIGS. 5, 8 and 13.

FIG. 14 is a partially sectioned end view, taken generally along line 14-14 of FIG. 5, of a subsection of the button magazine section which may be employed in delivering circular divider buttons as illustrated in FIG. 2.

FIG. 15 is a partially sectioned plan view, taken generally at line 15-15 of FIG. 5, illustrating the endless belts employed by the magazine subsection of FIG. 14.

FIG. 16 is a top plan view of another subsection of the button magazine section employed in delivering rectangular reflector buttons of the type shown in FIG. 2.

FIG. 17 is a fragmentary side view of the button magazine illustrated in FIG. 16.

FIG. 18 is a fragmentary, partially sectioned view, taken generally along the line 18-18 of FIG. 16, illustrating the ejecting mechanism employed by the magazine subsection of FIGS. 16 and 17. FIG. 19 is a partially sectioned end view of the magazine subsection of FIGS. 16 through 18, illustrating a manually actuated locking mechanism for retaining the subsection in an operative disposition.

FIG. 20 is a fragmented, partially sectioned view, taken generally along line 20-20 of FIG. 4, illustrating a portion of the button orienting mechanism provided for the gated track employed for orienting and conveying the buttons between the magazine section and the gating section of the machine.

FIG. 21 is a somewhat enlarged cross sectional view taken along line 21-21 of FIG. 4, illustrating the two channels and interposed knife edge employed in delivering circular buttons on edge from the magazine subsection of FIG. 5.

FIG. 22 is a plan view, on a somewhat enlarged scale, of the brush employed in cleaning surface areas preparatory to receiving adhesive applied by the adhesive applicator of FIG. 8.

FIG. 23 is a partially sectioned side elevational view of the structure illustrated in FIG. 22.

FIG. 24 is a partially sectioned front view, on a somewhat enlarged scale and taken generally along line 24-24 of FIG. 23, of the brush of FIGS. 22 and 23.

FIG. 25 is a partially sectioned side view of the guide boom forward portion of the vehicle illustrating boom structure employed in shifting the brush of FIG. 24.

FIG. 26 is a partially sectioned fragmentary end view of a portion of the structure of FIG. 22.

FIG. 27 is a partially sectioned view taken generally along line 27-27 of FIG. 23, of the control linkage employed for shifting the brush, as shown in FIGS. 22 and 23.

FIG. 28 is a top plan view taken generally along line 28-28 of FIG. 13.

FIG. 29 is a partially sectioned plan view taken generally along line 29-29 of FIG. 13.

FIG. 30 is a partially sectioned plan view taken along line 30-30 of FIG. 13.

FIG. 31 is a schematic diagram of the machine control circuit and circuit associated actuators.

FIG. 32 is an enlarged perspective view of a cam operated gang-switch employed in the circuit illustrated in FIG. 31.

FIG. 33 is a modified button magazine subsection which may be employed in delivering circular divider buttons with the machine of FIG. 1.

FIG. 34 is a sectioned elevation of a portion of one of the modified button magazines taken generally along line 34-34 of FIG. 33.

FIG. 35 is a partially sectioned, fragmentary elevation of a modified form of the glue applicator and button ejector mechanism as may be employed by the machine of FIG. 1.

FIG. 36 is a cross-sectional elevation taken generally along line 36-36 of FIG. 35.

FIG. 37 is a fragmentary plan view of the forward portion of the vehicle, illustrating successive positions for the boom and the brush.

BRIEF DESCRIPTION OF THE PREFERRED EMBODIMENT

General Description

As illustrated in FIG. 1, the machine embodying the principles of the present invention is an automated, self-contained and motorized vehicle which is steered in a convenient manner for driving the vehicle along a given surface, such as a surfaced highway. While the machine of FIG. 1 is to be employed in depositing "Bott's Dots" or lane-divider buttons along lane-divider lines in a pattern similar to that illustrated in FIG. 2, it is to be understood that the machine may be employed to lay similar buttons in any desired combination along any given surface for any desired purpose.

The machine, illustrated in FIG. 1, is provided with a power and steering section designated 10, which includes an internal combustion engine of a convenient design, an associated drive train and convenient vehicle steering mechanism mounted on a wheel supported frame, whereby the vehicle may be propelled along selected surfaces. Since the power plant and drive train form no specific part of the instant invention, a detailed description thereof is omitted.

Immediately preceding the power and steering section 10, the machine is provided with an adhesive button applicator section 20, which functions to deliver and apply to the highway surface adhesive supplied from pressurized sources, such as heated pots 22, and buttons delivered from an adjacent button magazine section 30. As various types of adhesive pots may be employed, as desired, and since such pots are commercially available, a detailed description thereof is also omitted in the interest of brevity. In practice, an operator steers the vehicle so that it is caused to follow a selected lane-divider line so that the buttons are caused to be delivered from the section 30 to the section 20 and thereupon deposited in globs of the adhesive delivered from the pots 22 to the surface of the highway. In order that the adhesive may be deposited in cleaned areas, a power driven brush 32 is oscillated into and out of engagement with the surface at predetermined intervals.

While it totally is feasible to employ the machine to apply buttons of a single configuration, prevailing requirements demand that the machine be able to employ two types of buttons, namely the hereinbefore described circular ceramic buttons and the generally rectangular buttons having the planar reflecting surfaces. Therefore, the magazine section 30 is provided with magazine subsections 34 and 36 for retaining both types of buttons to be applied.

Both the circular and the rectangular buttons are delivered from the magazine 30 to an inclined gated track, generally designated 38, FIG. 3, and deposited within the adhesive and button applicator section 20. Passage of the buttons, of both aforementioned types, through the gated track is inhibited by an advance gating section, generally designated 40. This section sequentially releases the buttons for delivery to a final gating and adhesive applicating section, generally designated

42, which serves to deliver the adhesive and buttons to the spot cleaned on the receiving surface of the highway.

Therefore, it should be readily apparent that as the vehicle of the present invention advances along a highway surface, the brush 32 spot cleans selected areas of the surface, arranged at predetermined intervals, applies adhesive to the cleaned areas and finally applies and seats the buttons as they are selectively delivered from the magazine section 30, to the final gating section 42, via the gating section 40 of the gated track 38.

BUTTON MAGAZINE

As described, in order to supply the lane-divider buttons of both the aforementioned types, the magazine section 30 conveniently is divided into the two magazine subsection 34 and 36. As shown in FIG. 3, the magazine subsection 34 includes a receptacle of a boxlike structural configuration into which the circular buttons randomly are deposited.

As a practical matter, the machine is intended to deliver eight circular buttons for each rectangular button. Therefore, the capacity of magazine subsection 34 normally is much greater than the magazine subsection 36 and includes parallel side and end walls 44 and 46, respectively, forming a boxlike receptacle 49 having a horizontal bottom wall 48 for supporting the circular buttons therein.

The bottom wall 48 is divided into two coplanar sections having an elongated conveyor belt 50 disposed therebetween and trained about an idler roller and a driven roller 54. These rollers are, in practice, driven through a convenient motor and chain drive coupling 55 in a manner such that the upper run of the conveyor belt continuously advances buttons towards one end of the receptacle 49, which serves as the discharge end of the receptacle, whereby the buttons continuously are advanced to be discharged from the magazine subsection 34.

As best illustrated in FIGS. 5, 6, 14 and 15, the discharge end of the receptacle 49 includes a pair of coplanar, vertically disposed wall sections having a driven agitator belt 56 disposed therebetween. The agitator belt 56 is operatively supported by an idler roller 58 and driven roller 60 in a manner such that a vertical run of the belt is in communication with the buttons retained and continuously advanced within the magazine receptacle.

It is intended that the belts 50 and 56 cooperate for serially delivering the buttons from an opening 61, FIG. 5, formed at the discharge end of the receptacle of magazine subsection 34. Therefore, the belt 56 also is driven by the motor and chain drive coupling 55 and is driven in a manner such that the run thereof adjacent to the buttons within the receptacle 49 is advanced in a vertical direction as the randomly oriented buttons simultaneously are advanced by the conveyor belt 50, whereby the buttons are continuously agitated. As the belts are spaced a distance sufficient for accommodating passage of only one button at a time, it can be appreciated that the agitator belt 56 continues to reorient or "stir" the buttons as they are delivered by the belt 50. The buttons thus become horizontally aligned and properly seated relative to the belt 50 whereupon passage through the openings 61 is accommodated and the buttons are thereupon serially delivered from the receptacle 49.

In practice, it is preferable to mount the agitator belt 56 within a housing defined by walls 62. These walls are provided with convenient openings for affording access to the belt 56 and its supporting rollers. Adjacent to the opening 61 the housing is provided with a depending pivotally hinged trap door 64, FIG. 5, which serves as a "bang board" for intercepting the buttons as they are discharged from the opening 61, whereupon the buttons crop in a vertical direction to be deposited on edge within the uppermost portion of the gated track 38 disposed adjacent thereto.

While the circular buttons are delivered to the gated track 38 from the magazine subsection 34, the magazine subsection 36 simultaneously serves to deliver the rectangular buttons to the gated track 38 at appropriate intervals between the delivery of the circular buttons.

As better illustrated in FIGS. 1 and 3, the magazine subsection 36 includes a plurality of adjacent channular segments forming a plurality of vertically arranged chutes 66, coupled into a unitary button dispenser 68. As best shown in FIGS. 16 through 19, the chutes 66 of the dispenser 68 are arranged in an in-line and contiguous relationship and receive therein vertical stacks of rectangular buttons to be retained therein and subsequently dispensed thereby.

As shown, the dispenser 68 includes four chutes 66, however, it should readily be apparent that the dispenser 68 may include any convenient number. The chutes 66 receive the rectangular reflector buttons deposited therein from the uppermost end in a manner such that the buttons are retained by the chutes in vertically aligned stacks and are discharged, in orthogonal displacement, at a discharge station 70 and delivered to an extended portion 71 of the track 38.

The discharge station 70 includes a convenient structure defining a button receiving chamber 72 having a button receiving and supporting surface 73 into which the buttons are permitted to drop from the chutes 66. Mounted for reciprocation along the surface 73, within the receiving chamber 72, there is a button ejector ram 74. This ram includes an uppermost button supporting surface 76 and a vertical "kicker" face 78. The ram is aligned for reciprocation in a plane common to the adjacent portion 71 of the gated track 38 in order that the buttons may be delivered thereto from the dispenser 68. It is to be understood that as the ram 74 is retracted or drawn outwardly relative to the chamber 72 a reflector button is permitted to drop and seat within the chamber so that as the ram 74 is extended its kicker face 78 engages the horizontal edge portion of the button and advances it towards the section of the gated track. As the ram is extended into the chamber along the surface 73, the surface 76 thereof engages the lowermost surface of the next-in-line button retained within the chute so that as the ram 74 is inserted its surface 76 serves to support the stack of reflector buttons while the button engaged by the kicker face 78 is being ejected or conveyed from the chamber.

While various means can be employed in driving the ram 74, a convenient actuator 80, including a rectilinearly reciprocating pneumatic piston, has been employed quite satisfactorily.

In practice, each of the chutes 66 is filled with a stack of buttons to be successively delivered. Therefore, it is necessary, in order for all of the buttons to be delivered from the dispenser 68, for the chutes 66 to be adjustably aligned with the chamber 72. This is achieved by providing a tracklike supporting base 82, including convenient dispenser supporting surfaces arranged thereon and adapted releasably to receive in supporting engagement therewith supporting lugs 83 which depend from the walls of the dispenser 68. It is to be understood that the dispenser may be adjustably indexed or horizontally displaced along the supporting base for aligning the various chutes with the chamber, while being continuously supported by the tracks of the base.

In order to secure the dispenser 68 in an appropriate disposition relative to the station 70, a spring-biased toggle linkage, including a conveniently pivoted locking lug 86, FIG. 19, is provided and employed for engaging one of a plurality of stop surfaces defined by appropriately formed openings 88, FIGS. 16 and 19, for retaining the dispenser in its desired relationship relative to the receiving chamber 72. Where desired, it is to be understood that the dispenser may include laterally extended bearing supports 89 for assisting in establishing and maintaining a vertical alignment for the chutes 66.

It will be appreciated that the button magazine section 30 is divided into subsections 34 and 36, which include the button receptacle 49 and the button dispenser 68 which together serve to deliver both types of the divider buttons to the gated track 38. While the circular buttons are delivered in a continuous manner from the opening 61 of receptacle 49, the rectangular buttons are delivered from the chutes 66 of the dispenser 68 in a selected sequence, the timing of which is dictated by controlling the rectilinear reciprocation of the button ejector ram 74.

BUTTON ORIENTING MECHANISM

As illustrated in FIG. 3, the adhesive and button applicator section 20 also includes the gated track 38 which delivers the buttons to the final gate and adhesive applicator section 42. In practice, the gated track 38 also serves as a convenient mechanism for orienting the buttons prior to a delivery thereof to the gating section 40. This particularly is true with respect to the circular buttons delivered from the magazine subsection 34.

As best illustrated in FIGS. 4 and 5, the gated track 38 includes a steeply inclined button receiver 90 disposed adjacent the opening 61, beneath the bang board 64, so that the buttons are caused to be caught by the receiver 90 as they are dropped from the discharge end of the receptacle 49.

The receiver 90 is of a V-shaped channular configuration terminating in a bifurcated channular portion to establish diverging paths for the buttons. The receiver includes a first inclined wall 92 and a second inclined wall 94 joined along their adjacent marginal portions to form a channular support such that the circular buttons are caused to be oriented to rest on-edge, or upon their peripheral surfaces, as they are received within the receptacle 90.

As the circular buttons are deposited in the receiver 90, the planar supporting surfaces thereof are engaged by one of the walls 92 or 94, FIG. 23, depending upon their orientation as they come to rest. The path selected by each of the buttons as it is delivered from the receptacle along the inclined receiver is determined by the particular wall against which the planar surface thereof rests as the walls 92 and 94 diverge. A knife edge 96 disposed between the inclined walls serves to establish the bifurcated path for the buttons. The knife edge is provided with diverging surfaces 98, FIG. 21, for assuring that the buttons are directed along the paths defined by the walls 92 and 94. The wall 94 is so configured as to establish an arcuate inclined path, turned through 90°, for delivering the buttons to the gate section 40, FIG. 5, while the wall 92 is abruptly terminated so that the direction of the path of buttons is caused to be altered as the buttons are delivered to the gate section.

As each button is advanced from the receiver 90, its plane of orientation is rotated through approximately 90° so that the button is caused to rest upon its planar supporting surface, as it is directed to a button delivery section 100 of the gated track 38, FIG. 20. Should the button initially rest on its edge surface, with its planar surface being in a "leaning" engagement with the wall 92, as it is advanced from the button receiver 90, the lowermost portion will engage a vertically extended lip 101, FIG. 20. This lip is provided at the termination of the wall surface 92 and is, in effect, a truncated extension of the wall 92 which serves to "trip" the button or engage and retard downward advancement of the lower peripheral surfaces of the button while accommodating a rotation thereof in its plane of orientation under the influence of gravity so that its surface of support is translated from its arcuate edge surface to its planar surface.

As illustrated in FIGS. 4, 5 and 20, the buttons are delivered to the delivery section 100 of the gated track 38, which further includes a downwardly inclined button delivery surface 102 adapted to support the buttons as they slidingly are advanced on their planar surfaces. In order to preclude a "stacking" of the buttons as they are delivered along the surface 102, an elongated lip 103 is disposed above and at each side of the surface in parallel relationship therewith. The spacing established between the surface 102 and the lip 103 is sufficient to accommodate passage of only one of the buttons at any given time for thereby maintaining serial alignment of the buttons as they are delivered along the track. To assist in arranging the buttons in serial alignment, a resilient rake 104 having a terminal portion 105 arranged adjacent to the throat of the section 100 is provided to engage the top of the buttons as they are displaced therebeneath so that superpositioning of the buttons entering the section 100 effectively is precluded.

Therefore, it should be readily apparent that as the buttons are discharged into the receiver 90 and caused to rest with

their planar surfaces lodged against either of the wall surfaces 92 or 94, they ultimately are oriented in a manner such that they are caused to rest on their planar surfaces as they are delivered to the delivery section 100 of the track 38.

As a matter of interest, the convex or domed surface of the buttons, near the periphery thereof, engages one of the walls of the receiver 90, as the buttons simultaneously are contacted thereby, thus to force the buttons to rest with the planar surface thereof in engagement with the surface of the opposite wall. This is achieved simply by shaping the V-shaped receiver in a manner such that each button rests on its periphery at the bottom portion of the receiver with the convex surface preventing the button from attaining an orientation where the center of gravity is shifted to the opposite side thereof as it is advanced while supported on its periphery.

In addition to the receiver 90, the gated track 38 also includes a receiver 108, FIGS. 4 and 18, formed in the extended portion 71 of the track 38. This receiver serves to receive and align the rectangular buttons as they are delivered from the dispenser 68. The receiver 108 is of an inclined, arcuate, channular configuration for receiving and delivering the buttons from the dispenser 68. As a practical matter, a holdown strap 109, FIG. 5, has been provided for assuring the retention of the buttons within the receiver 108 as the rectangular buttons are oriented with a leading edge thereof being transversely aligned with respect to the receiver.

In addition to the delivery section 100, the gated track 38 includes an additional delivery section 110, FIG. 4, which is aligned with the receiver 108 for accepting and delivering the rectangular buttons to the gating section 40 of the gated track 38.

The delivery section 110 is of a configuration quite similar to the delivery section 100 of the track 38, in that it includes a pair of spaced holdown lips 112 aligned in spaced parallel alignment with a button supporting surface 114. The holdown lips are spaced from the supporting surface a distance sufficient to accommodate passage of only one of the rectangular buttons therebetween in order to inhibit any tendency for the buttons to become oriented in a superimposed or an overlapping relationship as they are delivered to the gating section 40. However, since the rectangular buttons are delivered one at a time from the dispenser 68, there is little likelihood that the buttons will accumulate prior to their being introduced into the delivery section 110. Therefore, no rake is employed for the delivery section 110.

In view of the foregoing, it is to be understood that the circular buttons are delivered to the receiver 90 while the rectangular buttons are delivered into the receiver 108. From the receivers the buttons are delivered to the delivery sections 100 and 110 in a manner such that they are delivered in a single file to the gating section 40, whereat both types of buttons are arrested for subsequent delivery to the final gate and adhesive applicator section 42.

GATING SECTION

As best illustrated in FIGS. 4 and 11, the gating section 40 includes a pair of advance gates 116 and 118 which serve to arrest the buttons as they are delivered by the delivery sections 100 and 110 of the gated track 38. Since each of the advance gates 116 and 118 are of similar design and function in a similar manner, description of a single one of the gates is deemed sufficient to provide a complete understanding of the invention. However, it is to be understood that the gates 116 and 118 are actuated at appropriate intervals in the machine's cycle of operation for delivering both types of buttons whereby they may be applied to the surface of the highway in a predetermined sequence.

Turning for a moment to FIG. 8, wherein the gate 116 of the gating section 40 is illustrated, it is to be noted that the gate operatively is arranged adjacent to the delivery end of the delivery section 100. In practice, the advance gate 116 includes a pivotally supported rocker arm 120, arranged above

the button supporting surface 102 and includes a pair of downwardly directed button intercepting lugs 122. These lugs may be of any convenient design so long as they may be disposed against the button supporting surface 102 in a button intercepting disposition. It is intended that the rocker arms 120 serve as an escapement mechanism for accommodating a passage of only one of the buttons at each cycle of activation thereof. Therefore, the rocker arm operatively is supported for pivotal rotation about a transverse pivot 124 with the lugs 122 being arranged at the opposite ends thereof so that they alternately are displaced into engagement with the button surface 102 for intercepting the buttons as they are delivered along the delivery section 100 of the gated track 38.

While various devices may be employed for oscillating the rocker arm 120, a convenient spring-loaded pneumatic actuator 126, including a reciprocating shaft 128, serves quite satisfactorily for this purpose.

The extended end of the shaft 128 is coupled through a suitable clevis 130 to the rocker arm 120 so that the arm is oscillated about its pivot 124 as the shaft 128 is reciprocated relative to the actuator housing, as best illustrated in FIGS. 8 and 13. In other words, when the shaft 128 is extended by the actuator 126, a lug 122 is forced against the surface 102 so that the outermost surface of the leading lug, FIG. 8, serves to engage the periphery of a circular button being delivered from the delivery section 100 of the track 38, and when the shaft 128 is retracted, this lug is elevated and the lug located at the opposite end of the rocker arm is depressed for causing that lug to engage the surface 102 in a button arresting disposition. With the rocker arm thus depressed, the button illustrated in FIG. 8, is permitted to advance to the innermost surface of the depressed lug 122 as shown in FIG. 13. Upon the next activation of the cylinder 126, for extending the shaft 128, the rocker arm 120 is again rotated, this time in an opposite direction about the axis 124 for elevating the depressed button 122 and depressing the elevated lug, so that the button retained against the inner surface of the depressed lug now is permitted to advance along the surface 102, while the outermost surface of the lug being depressed is brought into a blocking engagement with the periphery of the next-in-line circular button being advanced along surface 102. Therefore, it should readily be apparent that only one button at a time is permitted to escape through the escapement of the advance gates 116 and 118.

The timing of the operation of the gates 116 and 118 is such that the gate 118 is actuated to deliver a rectangular button once for every eight circular buttons delivered by the gate 116. Hence, circular buttons are applied in strings of four, on 3-foot centers, with an interval of 15 feet being established between the strings, while within alternate intervals, midway between the strings, there is deposited a rectangular button. Therefore, the gates 116 and 118 are operated in a manner such that four circular buttons are delivered in sequence, with no rectangular buttons being delivered to the interval between the strings, for a first cycle of the machine, while during the next cycle four circular buttons are delivered on 3-foot centers, followed by an operation of the advance gate 118 so that a reflector button is caused to be delivered midway of the interval between the strings. Of course, as may be readily appreciated, the spacings, the intervals and the types of buttons delivered may be altered as is required for meeting various standards which may be imposed for safety and other reasons.

Once the buttons escape from the advance gates 116 and 118, they are immediately delivered along the surfaces 102 and 114 through a track converging terminal section 135 of the track 38 to a final gate 136. The section 135 serves to unite the delivery sections of the gated track 38 so that the gate 136 serves to arrest the buttons as they are discharged from either of the advance gates 116 and 118. The purpose of the final gate 136 is to position the buttons at the terminal section of the gated track for discharge to the surface of the highway.

The final gate 136 includes a button arresting lug 138 which is pivotally mounted about a support 139 and is spring biased by a tension spring 140, FIG. 8, in a manner such that the lug continuously is urged in rotation in a direction for exposing the lug in a button intercepting disposition. The spring 140 is connected to the lug by an operating lever 141 in a manner such that it applies a force to the lug 138 suitable for retaining a button delivered from either of the gates 116 and 118. However, it is intended that the lug 138 being pivoted downwardly as a button forcibly is driven thereover. Hence, once a button is delivered from either of the gates 116 or 118, it is arrested at the final gate 136, in its downward displacement through the terminal section of the track 38, by the lug 138. This lug subsequently is overridden for pivoting the lug against the action of the spring 140 as a button is discharged from the machine.

It is to be understood that both the circular buttons and the reflector buttons are arrested at the ends of the delivery sections of the gated track by the oscillatable rocker arms 120 of the gates 116 and 118 of the gating section. As the rocker arms 120 are oscillated, the buttons are delivered to the final gate 136 through the terminal section 135 and there arrested by the lug 138. Since the gates 116 and 118 are timed for selective sequential operation only one button will be present at the final gate 136 at any given instant in time. At an appropriate instant, the button forcibly is driven against the lug causing it to rotate against the action of the spring 140 so that the button may be ejected.

BUTTON EJECTOR

In order to eject a button from the gate 136, there is located within the adhesive and button applicator section 20 a button ejector 150 which serves forcibly to eject buttons which have been arrested and positioned at the final gate 136. The ejector 150 includes a spring-biased head 152, FIG. 8, which includes a kicker face 154 adapted to engage the rearmost peripheral surface of a button retained within the final gate 136. The head 152 is pivoted for oscillatory rotation about a pin 156 and urged in rotation by a compression spring 158 which permits the head 152 to be depressed and serves to force the head 152 upwardly into an operative disposition relative to the rearmost peripheral surface of buttons retained in an arrested state.

As best shown in FIGS. 10 and 11, an ejector track 159, includes coplanar, parallel track sections 160 disposed at opposite sides of the reciprocating ejector head 152. Therefore, as the buttons are delivered from the gates 116 and 118 they serve to depress the head 152, against the action of the spring 158, as they advance along the track sections 160 to be intercepted at the gate 136, and upon activation of the ejector 150 the head 152 is advanced into driving engagement with the trailing peripheral edge of the button retained at the gate 136, for driving the button in opposition to the bias of the spring 140 for causing the button to be ejected from the machine to the surface of the highway.

The ejector head 152 is supported for reciprocation by an ejector head mounting bracket 162, which in turn is supported by a U-shaped coupling 164. The coupling 164 includes a first downwardly depending leg 166 and a second downwardly depending leg 168. For achieving translational displacement, for thereby imparting rectilinear reciprocation to the ejector head 152, the leg 166 is connected by suitable coupling means, including a screw-threaded nut 170, to a reciprocating shaft 172 of a double-action pneumatically activated actuator 174. As the shaft 172 of the actuator 174 is extended, an advancing force is applied to the ejector head 152, through the coupling 164 and mounting bracket 162 connected therewith and as the shaft is retracted the head is repositioned to receive the next button thereover.

Therefore, the button ejector 150 is activated through the reciprocating actuator 174, which serves to reciprocate the support for the ejector head 152 so that the head 152 is caused to be driven in first direction for ejecting the button through

the final gate 136 and in an opposite direction, by a retraction of the shaft, for seating the head in an operative position ready to receive the next-in-line button from the advance gates 116 and 118.

GLUE APPLICATOR

As the buttons are ejected, by the button ejector 150, to the surface of the highway, it is necessary that an adhesive be applied to the highway surface prior to receiving an ejected button. However, since it is totally impractical to apply a "string" of adhesive, the machine is provided with an intermittently actuated adhesive applicator 176 which applies the adhesive as large drops, often called "glob." The adhesive applicator is best illustrated in FIGS. 8, 10 and 12.

While various adhesives may be applied as found practical for securing the buttons to the surface of the highway, as presently employed the adhesive is an epoxy which is delivered in a mixed state from the pressurized pots 22, to the applicator 176, whereby the applicator functions to deposit the mixed epoxy in a heated condition, although this may be varied, as desired. Since epoxy is being used as the adhesive for securing the buttons to the highway, it is desirable to deliver the buttons to the epoxy immediately upon an application of the adhesive to the surface of the highway. Therefore, the adhesive applicator 176 is mounted near the discharge end of the track section 159, near the button ejector 150 particularly, so that as a button is ejected from the machine it is caused to be deposited in the adhesive before aging occurs.

As illustrated in FIG. 8, the adhesive applicator 176 includes a barrel 178 having mounted therein a reciprocating piston head 180, purpose of which is to force adhesive deposited within the barrel towards the lowermost end thereof. The lowermost end of the barrel is so formed as to include an end wall 181 paralleling the plane of the adjacent surface of the highway. Consequently, the wall 181 is in a plane which is diagonal to the longitudinal axis of the barrel 178. As best shown in FIG. 12, the end wall includes a discharge port 182 having a discharge axis extending vertically with respect to the plane of the surface of the highway so that the adhesive is discharged from the barrel 178 in a vertical direction and deposited as a glob on the adjacent surface of the highway.

The adhesive is delivered to the barrel 178 through a convenient orifice 184 and substantially fills the barrel when the piston head 180 is fully retracted. The adhesive is delivered under pressure to the orifice 184 via a pressure line 186 which extends to a suitable mixing unit 188 best illustrated in FIG. 13. The mixer 188 is of any convenient design which receives epoxy and "hardener" or catalyst from the pots 22 by way of pressure lines 190. As a matter of convenience, the pots 22 are "pumped" by a convenient epoxy unit, generally designated 192 in FIG. 3.

Since the mixer 188 and the associated pressure and supply pots 22, as well as the unit 192, are of a commercially available design, a detailed description thereof is omitted in the interest of brevity. However, it is to be understood that the unit 192 is of a type which supplies epoxy and a hardener by way of the pressure lines 190 to the mixer 188 to be mixed in appropriate proportions.

In practice, the mixer 188 includes an auger unit which continuously is revolved for mixing the epoxy and its hardener. The mixed epoxy ultimately is discharged from the unit by way of a convenient pneumatic actuator 194. As the adhesive is delivered from the mixer 188 into the line 186 it is discharged under pressure and consequently is under pressure when introduced into the barrel 178 of the applicator 176.

Since the adhesive is delivered to the adhesive applicator 176 under pressure, it is necessary that a closure member be provided for closing and sealing the orifice 182. As best illustrated in FIG. 8, the closure member 196 is formed as a reciprocating closure plate 196 seated for reciprocation along conveniently formed tracks 198, whereby the orifice 182 may be opened and closed, by a displacement of the closure plate

196, whereby the adhesive may be delivered through the orifice 184 into the barrel 178 when the discharge port 182 is closed and sealed.

When the adhesive is to be deposited on the adjacent surface of the highway, the plate 196 is displaced along the tracks 198 for opening the discharge port 182 so that adhesive contained under pressure within the barrel 178 is caused to be delivered from the barrel of the applicator 176. At the opening of the discharge port 182, the head 180 is displaced in an axial direction through the barrel 178 for thereby advancing adhesive retained therewith for thus assisting in the depositing of a glob on the adjacent surface of the highway. At an appropriate point in the operation of the applicator, the discharge port 182 is closed, by effecting a reseating of the closure plate 196. At this time the head 180 is retracted to a reseated position adjacent to the uppermost end of the barrel 178 so that the barrel 178 is permitted to be charged with a preselected quantity of adhesive delivered under pressure from the mixer 188 through the line 186 and the port 184 to be deposited at the next actuation of the closure plate 196.

Under certain operative conditions it is feasible to interconnect the plate 196 with a drive for displacing the piston head 180 so that the plate 196 is operatively displaced for opening the discharge port 182 as displacement of the head 180 is initiated. However, in order to simplify adjustment and adhesive application control, it has been found advisable to employ separate actuator drive means for driving the head 180 and the closure plate 196.

In practice, therefore, the head 180 is connected with the leg 168 of the bracket 164 through a reciprocable drive shaft 200, which extends through a suitable orifice formed in one end of the barrel 178. As best illustrated in FIG. 12, the shaft 200 is seated and connected within the leg 168 of the bracket 164 by a connector suitable for achieving lost motion between the leg 168 and the shaft 200 as the shaft 172 of the actuator 174 advances the bracket 164. As the bracket 164 is advanced, the leg 168 thereof progresses along the shaft 200 until such time as the opposite leg 166 of the bracket engages the extended end of the shaft 200. As the leg 166 engages the extended end of the shaft 200, the shaft is driven downwardly through the barrel 178 of the applicator 176 for axially displacing the head 180 therealong.

In order to retract the piston head 180 to the uppermost end of the barrel 178, a suitable collar 201 is coupled to the shaft 200 by means of a convenient screw-threaded nut 202 so that as the bracket 164 is displaced in a retracting direction, the collar 201 engages the surface of the leg 168 for applying tension to the shaft 200 for withdrawing the piston head 180 relative to the barrel of the applicator 176.

Therefore, it is to be understood that when a button is seated at the final gate 136 and the shaft 172 of the cylinder 174 is extended for ejecting the button from the final gate, a predetermined travel of the bracket 164 is accommodated prior to the displacement of the head 180 relative to the barrel 178. However, at an appropriate point in the operation of the actuator 174, the head 180 within the barrel 17 is advanced by the bracket 164 for discharging adhesive from the applicator 176 through the open discharge port 182. Once an appropriate quantity of adhesive has been discharged through the port, the piston head 180 is retracted along the barrel to be received at the uppermost end thereof through a retracting activation of the actuator 174 for retracting the bracket 164.

While various means could be employed for supporting the shaft 200 and the associated bracket 164 for reciprocation relative to the barrel 178, a stationary guide rail 204 has been adopted which is supported at its opposite ends, by any convenient means, and is extended through both legs of the bracket 164 so that the legs of the bracket are supported and guided by the rail 204 as the bracket is reciprocated therealong. In addition to providing a desired support, the rail 204 very importantly serves as a guide means for assuring continued axial alignment of the shaft 200 as the bracket 164 is reciprocated whereby binding resulting from misalignment of the head 180 within the barrel 178 is effectively avoided.

In order that the discharge port 182 be opened by displacing the closure plate 196, a double-action pneumatic actuator 206, including a reciprocating shaft 207, is coupled with the plate 196 through a pivotal bellcrank link 208 and a pivoted linkage 210, FIGS. 12 and 13.

The linkage 210 includes a bearing supported coupling pin 212 fixed to the rearmost portion of the plate 196 and supported by offset bearing supports 214 arranged at the lowermost end of a pivoted lever 216. The lever 216 is mounted for oscillation about a fixed pivot bearing 218 with the uppermost end thereof being connected by a pivot pin 220 to the bellcrank 208 whereby actuation of the linkage 210 is achieved through an oscillation of the bellcrank 208 for effecting a reciprocation of the closure plate 196.

One arm of the bellcrank 108 is pivotally connected to the shaft 207 at a pivot pin 222, which serves to couple the bellcrank with the shaft 207 of the cylinder 206, while the opposite arm is coupled through a tension spring 224 to a fixed eyebolt support 226. The spring 224 acts to apply to the bellcrank a driving force directed in a manner such that the bellcrank is urged in rotation about its pivot pin 222.

As the shaft 207 is extended, the spring 224 is tensioned and serves to apply a force to the bellcrank 208 for driving the bellcrank in rotation about its pivot pin 222. However, in order to impart to the linkage 210 a desired "fast" response, rotation of the bellcrank initially is opposed by the bearing 218, acting through the lever 216 at the pivot pin 220, and subsequently released for accommodating rotation under the influence of the tensioned spring 224. This is achieved as the pivot pin 220 first is advanced through a vertical plane extending through the axis of the bearing 218, while the pivot pin is retained in axial alignment relative to the shaft 207 and pivot pin 222, through the lever 216 acting on the bellcrank for applying a force acting in opposition to the force of the spring 224. Once the pivot pin 220 has advanced through the vertical plane, with the spring being tensioned thereby, the lever 216 becomes ineffective for acting on the bellcrank, whereupon the thus tensioned spring 224 is permitted to act on the bellcrank 208 and rapidly drive it about its pivot pin 222 for driving the plate 196 in a discharge port-opening direction with a "snapping" overcenter action. When the cylinder 206 is activated for retracting the shaft 207, the reversed action of the interrelated bellcrank and linkage 210 is imparted thereto for reseating the plate 196 in the discharge port.

The cylinder 206 conveniently is mounted relative to the adhesive applicator 176 by any suitable means including a plurality of screw-threaded studs which serve to support the barrel of the cylinder in a predetermined alignment relative to the linkage 210. Rectilinear reciprocation of the shaft 207 is controlled through a piston head 232 operatively connected with the shaft 207 and adapted to be displaced along the barrel of the cylinder 206 in response to an introduction of fluid under pressure at the opposite ends of the cylinder. This fluid is directed through pressure lines 234 connected with the barrel of the cylinder and communicating with a suitable fluid supply means.

Therefore, it is to be understood that in operation the discharge port 182 is opened and closed through an actuating displacement of the closure plate 196. This operation is achieved through an activation of the actuator 206 which drives the shaft 207 in reciprocation parallel to the longitudinal axis of the barrel 178. As the shaft 207 is extended, the bearing 218 acts to support the lever 216 and while accommodating a subsequent rotation of the bellcrank 208 about the pivot pin 222. At an appropriate point in its cycle of operation, the bellcrank is released and the tension spring 224 applies a driving force to the bellcrank for driving the pivot pin 220 downwardly. As the pivot pin 220 is forced downwardly in response to the action of the spring 224, a "snapping" effect is achieved for the bellcrank for thereby rapidly rotating the lever 216 about the bearing 218 for thus "kicking open" the discharge port 182. Pressurized adhesive within the barrel 178 is then forced through the open discharge port, as the piston head 180 is forced downwardly into the barrel, for thereby dis-

placing the adhesive. Once the head 180 and the shaft 207 are retracted within the cylinder 206, the plate 196 is reseated.

It is important to note that in seating the plate 196, the pivot pin 220 is displaced upwardly relative to the closure plate 196 and the bearing 218. As the bellcrank 208 is retracted, the lever 216 acts to force the bellcrank in a clockwise rotation, as viewed in FIG. 13. As the pivot pin 220 approaches a vertical plane passing through the center of the bearing 218, a tension force is applied to the spring 224 which acts to rotate the bellcrank 208 about the pivot pin 222 so that an "over-center" action is achieved in a reverse direction for "snapping" the closure plate 196 into a seated position.

Through the use of an overcenter effect, the plate 196 rapidly is opened and closed, whereby a "stringing" of the adhesive along the adjacent surface of the highway effectively is prevented, as the adhesive is caused to be applied in discrete globs of predetermined quantities. Buttons ejected from the final gate 136 subsequently are seated in the applied globs by a button seating means.

BUTTON SEATING APPARATUS

Within the adhesive and button applicator section 20 there is provided a pneumatic tire 236 mounted for rotation adjacent to the lowermost end of the gated track 38 so that the buttons discharged to the globs of adhesive, from the final gate 136, are caused to be discharged beneath the surface of the tire as the machine advances along the surface of the highway, whereby a downwardly directed button seating force is applied thereto.

The tire 236 is mounted for rotation about a convenient axle 238, FIG. 8, extended transversely of the machine at a preselected distance above the surface of the highway so that buttons ejected by the ejector 150 from the final gate 136 into a glob of adhesive may be pressed downwardly by the surface of the tire. As a practical matter, the tire 236 forms no supporting function, therefore the level of the downwardly directed pressure applied to the upper surface of the button is a matter of convenience and may be varied as required simply by elevationally adjusting the tire. It should be apparent that as the machine advances and a button is ejected from the gated track 38 into the adhesive applied by the adhesive applicator 176, the tire 236 is caused to roll over the upper surface of the button causing the button to assume a seated disposition within the glob of adhesive.

PIVOTED FRAME

The adhesive and button applicator section 20 is supported by a pivoted frame 240 formed of convenient rail members 241 extending obliquely downwardly from a bearing pivot 242 and terminating in a pair of horizontal rails 243. The rails 241 and 243 are joined in any convenient manner, such as by welding.

However, the bearing pivot 242 is coupled with a transverse beam 244 extending across the width of the machine. While any convenient means may be employed for coupling the bearing pivot 242 to the beam 244 a convenient right angle bracket 246 has been employed quite satisfactorily at each side of the frame 240. Therefore, it is to be understood that the frame 240 is pivotally coupled with the transverse beam 244 of the machine through the bearing pivot 242 mounted by brackets 246.

The lowermost portion of the frame 240 includes the horizontal rails 243 coupled by a transverse beam 248. The horizontal rails are, in turn, supported by a pair of spaced wheels 250, also mounted on the axle 238 as it is extended between the rails 243 in a supporting relationship therewith. While, not shown, it is to be understood that suitable bearing means are provided for the axle, whereby the frame 240 is supported above the ground by the wheels 250 as the machine is driven along the surface of the highway.

From time to time, it is found necessary to elevate the frame 240 for raising the various machine components supported

thereby above the surface of the highway. Such conditions occur when the vehicle is being repaired, maintained or when it is being driven along the highway for purposes of transporting the machine.

To achieve this elevation, a convenient actuator 254 is coupled between a pair of clevis couplings 255 and 256 of a convenient design. The barrel of the actuator 254 is coupled by the clevis 255 to the transverse main beam member 244 through a bracket 257 depending therefrom, while the clevis 256 is connected to a convenient bracket, not designated, fixed to the frame 240. The cylinder 254 is of any convenient design, however, it is to be understood that the cylinder is operatively connected with a pressurizing of fluid, through a line 258, and includes an extendible shaft 260 to which is fixed the clevis 256. In practice, the line 258 is operatively connected with a system source of pneumatic pressure.

Therefore, it should readily be apparent that when fluid is delivered from any convenient source, to the cylinder 254, via the line 258, the shaft 260 is extended, whereupon the frame 240 is lifted above the surface of the highway. Once pressure is removed from the pressure line 258, the weight of the frame and components supported thereby is sufficient for returning the fluid from the barrel of the cylinder for allowing the frame 240 to be seated as the frame is rotated about its bearing pivot 242.

It is important also to note that the sections of the gated track 38 are mated along the axis of rotation for the bearing pivot 242 so that when the frame 240 is in its lowermost position, the track sections are aligned for receiving and delivering buttons therethrough.

ROTARY BRUSH

The brush 32 of the machine includes a rotor 262, FIGS. 22, 23 and 24, supported for rotation about an axle 263. A plurality of rotatable steel discs 264 are mounted about the periphery of the rotor 262 by a plurality of pins 266, as best illustrated in FIG. 23, so that as the rotor 262 is rotated, at a predetermined rate, the discs 264 strike the surface of the highway for scoring the surface and thereby removing therefrom foreign matter, such as paint and road grime which tends to inhibit the adhering effects of applied adhesive.

The rotor 262 is driven in rotation by a plurality of associated V-belts 268 operatively coupled thereto through suitable sheaves 270 mounted on the axle 263, in any convenient manner, for establishing a drive coupling 272. The drive coupling is supported in driving alignment with the rotor by suitable bearing support means 273. The V-belt 268 also are trained around a plurality of driven sheaves 274 fixedly mounted on a powered shaft 276. This shaft is supported by suitable bearing structures, including conveniently mounted bearings 278 and 279 located at opposite sides of the sheaves 274 and of any convenient design. The bearing 278 is fixed to a pivotally supported frame 280 while the bearing 273 is secured to the distal end of an extended arm 282 of the frame which serves to support the rotor 262 and its associated sheaves 270. The bearing 279, on the other hand, is supported by an arcuately slotted right angle bracket 284 coupled to a longitudinally extending main beam 286 of the vehicle frame through a convenient bearing plate 287. The slotted bracket 284 includes an elongated arcuate slot 288, FIG. 22, which permits the distal end of the arm 282 to describe an arc about a pivot point 290. Where desired, the bearing 279 is coupled to the bracket 284 by means including convenient studs 292 extended through the slot 288 and openings conveniently found in the bearing housing so that the housing of the bearing 279, mounted on the plate 287, may be guided in displacement across the surface of the bracket, along a path defined by the slot and the studs extended therethrough. If desired, the housing 279 may be fixedly coupled to the bracket by the studs.

In order to accommodate the desired displacement of the bearing 279 within the drive train for the brush, there is pro-

vided a universal joint 294, at the pivot point 290. The universal joint is pinned by pins 298, between the drive shaft 276 and an output shaft 295 of a suitably geared, direction-change gear box 296. The output shaft 295 of the gear box 296, through the universal joint and the shaft 276, serves to drive the sheaves 274 so that for any location of the bearing 279 relative to the slot 288, driving rotation of the sheaves is accommodated.

In practice, the gear box 296 is mounted on a main beam 286 of the vehicle frame in fixed relation thereto. A drive shaft 200, FIG. 3, extends rearwardly along the beam reciprocated; of the frame, and is employed to power the gear box output shaft 295. The shaft 300 is coupled with the vehicle's engine through a conveniently arranged belt and sheave coupling 301 including a driven sheave 302 drivingly connected with a convenient engine output and with a driven sheave 303 through a V-belt 304, FIG. 3.

It is to be understood that as the engine or power plant of the vehicle is operated, the sheave 302 drives the sheave 303 through the V-belt 304 for imparting a determinable rate of rotation to the drive shaft 300 which rotation, in turn, is delivered to the output shaft 295 of the gear box 296. The gear box 296 may be geared for any desired rate of rotation, however, and as presently employed, the shaft 276 is driven at a one-to-one ratio relative to the shaft 300, with the selected speed-reduction being achieved at the coupling 301.

Therefore, it should be appreciated that the surface of the highway is cleaned through a rotation of the rotor 262 driving the disc 264 in engagement with the surface of the highway. Of course, as is readily understandable, it is highly undesirable continuously to clean a strip along the surface of the highway, since continued cleaning operation would impose excessive wear on the discs 264. Hence, it is preferred that the brush rotor 262 be elevated between areas which are to be cleaned to receive the adhesive. This elevation is achieved by a simple oscillation of the frame 380 about the drive shaft 276, whereby the arm 282 is caused to describe a series of arcs.

In order to achieve the desired oscillation, an arm 306 is fixed to the frame 380 and depends radially therefrom, relative to the axis of the drive shaft 276, to define a predetermined included angle with the arm 282. Hence, by imparting to the arm 306 a rate of rotation for driving the arm 306 in arcuate displacement about the shaft 276, the arm 282 also is caused to rotate relative to the drive shaft 276.

In order to achieve the desired displacement of the arm 306, a pneumatic actuator 308, FIGS. 5 and 23, having a barrel and reciprocating piston, including a shaft 309, is operatively coupled thereto. The barrel is mounted by means including a clevis and pin coupling 310 fixed to the bracket 257. At the extended end of the shaft 309 there also is fixedly secured a clevis and pin coupling 314 which serves for coupling the shaft 309 with the depending arm 306. Therefore, as the shaft 309 is extended, the arm 306, and consequently the arm 282, are rotated about the drive shaft 276 in a first given direction of rotation for achieving elevation of the rotor 262 for the brush 32. As the shaft 309 is retracted, relative to the barrel of the cylinder 308, the arm 306, and consequently the arm 282, are rotated in a direction to achieve a seating of the discs 264 against the upper surface of the highway.

While various means may be employed for achieving an adjustment of the extent of travel of the shaft 309, for thereby imposing a predetermined oscillation of the arm 282, a threaded adjusting rod 316 has been employed quite satisfactorily. As presently employed, the rod includes a T-handle 317 and a screw-threaded body fixedly secured within a coupling 318, by means including collars 319, fixed to the arm 306. The opposite end of the rod 316 is extended through an eye bracket 320 fixed to the barrel of the actuator 308. A stop nut 322, and its associated jam nut are adjustably positioned along the distal end of the rod, whereby extension of the shaft 309 is arrested by the engagement of the stop nut 322 with the eye 320 so that the extent of elevation afforded the rotor 262 of the brush is effectively dictated by adjusting the nut 322 along the rod 316.

Also, a stop nut 324 is mounted on the rod 316 and its associated jam nut is located between the eye bracket 320 and the coupling 318. This nut acts in much the same manner as the nut 324 to govern the extent of the retraction of the shaft 309 and adjustment is effectively dictated by similarly adjusting the nut along the rod 316.

Therefore, by adjusting the position of nuts 322 and 324 along the rod 316, relative to the eye 320, the extent of rotation imparted to the arms 306 and 282 is operatively controlled for dictating the elevation imparted to the rotor 262. The rotor 262, when in operation, is positioned above the surface of the highways at a point just sufficient for the discs 264 to engage and remove deposits of surface material from the surface of a highway.

Preferably, the actuator 308 is a spring-loaded pneumatic actuator including convenient pneumatic coupling means for connecting the actuator through pressure lines 326 with a source of pressurized fluid. Therefore, it is to be understood that the shaft 309 is driven in opposite directions for positioning the rotor 262 relative to the surface of the highway so that the discs 264 of the rotor 262 are brought into engagement with the surface of the highway at selected intervals to spot clean areas which are to receive a glob of adhesive from the adhesive applicator 176.

In operation, as the vehicle progresses along the surface of the highway, the rotor 262 periodically is elevated through an operation of the spring of the actuator 308 which forces the arm 306 of a frame 280 to rotate about the drive shaft 276 for thereby lifting the rotor through a rotational displacement of the associated supporting arm 282 and is positively driven into engagement with the surface as pneumatic pressures retract the shaft 309.

The rotor continuously is driven through the drive shaft 300, the gear box 296, the sheaves 274 and the V-belts 268, which act to impose a rate of rotation to the sheave 270 pinned to the drive coupling 272 for rotating the rotor. As the rotor is caused to strike the surface of the highway, the discs 264 frictionally score and thus clean the surface of the highway. The duration of the thus initiated cleaning operation is determined by the operation of the actuator 308, and the pressure applied thereby is determined by the adjustment of the adjusting rod 316.

STEERING LINKAGE

Steering of the vehicle along selected highway surfaces is achieved through control of the position of a pair of front wheels 327. A pivotally mounted bellcrank 328 is coupled with one of the front wheels 327, FIG. 22, by means including a wheel-drive coupling pin 329. The bellcrank 328 also is connected through a tie rod 330 and a pivot pin 332 to the opposite wheels of the pair at a pivot pin 334 and throw arm 336, FIG. 37, whereby simultaneous control of the wheels 327 is achievable for steerable purposes.

In order to impart steerable control to the wheels 327, an adjustable push-pull link 338 is coupled with the bellcrank 328 at a pivot 340. The link 338 is reciprocated for oscillating the bellcrank for imparting angular displacement to the wheels 327 of the frame.

Reciprocation is imparted to the push-pull link 338 by an oscillating arm 342, FIG. 23, having a pivot pin 344 interconnecting one end of the arm 342 with an adjacent end of the link 338. The opposite end of the arm 342 is pinned to a bearing supported rotatable shaft 346, which is coupled to the frame by means including a suitable bearing 347. To impart rotation to the shaft 346, a push-pull link 348 is extended rearwardly to the power and steering section 10 and is adapted to be reciprocated to impart oscillation to the shaft 346 for achieving a steerable of the vehicle through a throw arm 350 pinned at one end to the shaft 346 and releasably coupled at its opposite end to the push-pull link 348 by means including an adjustable link 352.

As best illustrated in FIG. 3, the push-pull link 348 also is operatively coupled to be reciprocated by linkage including a pivot pin 354, a connected bellcrank 356 supported at a pivot 358, and a drive link 360 coupled between the bellcrank 356 and a steering throw arm 361, by suitable pivot pins 362. The throw arm 361 is oscillated by means including a steering wheel 364 for thereby imparting reciprocation to the link 360 whereby the bellcrank 356 is caused to oscillate about the pivot 358 for imposing rectilinear reciprocation to the push-pull link 348, which oscillation ultimately is transmitted to the bellcrank 328 connected with the wheels 327 of the vehicle.

Under certain road conditions, it is advisable that the brush 32 be displaced laterally with respect to the frame of the vehicle so that the brush may be seated against the highway surface along a highway divider line even though the frame of the vehicle is offset relative thereto, due to the steerable of the vehicle.

This displacement is achieved simply by releasing the bearing 279 at the bracket 284 and coupling the bearing with the arm 350 through an adjustable push-pull link 366, FIG. 22. The link 366 is coupled to the plate 287 supporting the bearing 279 by a suitable bracket 368 and to the arm 350 by an adjustable coupling 369 including a setscrew 370. This coupling permits the push-pull link 366 to be released, and/or lengthened and shortened relative to the arm 350 for controlling the displacement of the bearing 279, and consequently the position of the frame 280 as it is pivotally displaced about the pivot point 290.

Hence, it is to be understood that the relative position of the brush with regard to the center of the frame may be varied by varying the extent of arcuate displacement imparted to the bearing structure 279 through the push-pull link 366.

Therefore, it should readily be apparent that the brush 32 is displaced through the cooperation of the rod 348 acting through the rod 366, whereby the position of the brush 32 relative to the divider line is maintained, even in instances where the vehicle's relative position is displaced.

In instances where the push-pull link 366 is coupled with the push-pull link 348, the vehicle may move to either side of the lane-divider line. However, as lateral displacement for the frame of the vehicle occurs, the brush 32 tends to follow the divider line due to its displacement about the pivot point 290 in response to the force applied thereto by the push-pull link 366.

It should be understood that lateral displacement of the brush 32 may be eliminated simply by releasing the setscrew 370 and securing the studs 292.

GUIDE BOOM

As an aid in maintaining the vehicle in centered alignment relative to the divider line to which the vehicle is applying lane-divider buttons, the machine is provided with a boom 372 extending forwardly of the machine which serves as a guide for achieving desired alignment of the machine relative to the divider line. The extended end of the boom 372 is supported by a caster-supported frame 374 which in operation is positioned for displacement along the divider line.

The innermost end of the boom is pivotally coupled with the frame by means including a double-acting clevis 375 joined to the frame by convenient pivot pins 376 and 377 which serve to join the boom 372 with the frame. Lateral control for the boom 372 is effected through a drive link 379 interconnected with the foremost end of the push-pull link 348. This link is so coupled with the boom 372 that as the link 348 is reciprocated, the link 379 is displaced through an arc for driving the boom 372 in lateral displacement about the pin 376, for thereby guidingly displacing the boom 372 relative to the clevis pivot point. If desired, the boom 372 may be removed from the vehicle by uncoupling the clevis 375.

Therefore, it should readily be apparent that with the housing of the bearing 279 being connected with the arm 350, through the link 366, the vehicle may be steered along the sur-

face of the highway and as steerage correction is achieved, by angularly displacing the front wheels of the vehicle, the boom 372 is laterally displaced about the pivot pin 376 of the clevis 375.

As the caster-supported frame 374, FIG. 37, is maintained in alignment with the divider line of the highway, through a displacement of the link 378 by the push-pull link 348, the brush 32 laterally is displaced with respect to the machine in response to a displacement of the rod 348 as the direction of travel for the wheels and the positioning of the boom is altered by an operator controlling steerage of the vehicle.

MACHINE CONTROL SYSTEM

AS the machine is advanced for applying buttons along a lane-divider line of a selected highway, it is necessary to accommodate a sequential operation for the oscillation of the brush, the application of globs of adhesive to cleaned areas, and the ejection of the buttons into the deposited globs of adhesive. Furthermore, since application of each button requires that the surface of the highway be cleaned, the adhesive be applied and the button be deposited in the applied adhesive, the sequential operation of the machine must be repetitive as well as sequential. As shown, particularly FIG. 31, a plurality of electrically driven valves 380, of similar design, are provided for controlling the operation of various actuators employed in operating the various machine mechanisms, including the brush 32, ram 74, the advance gates 116 and 118, the button ejector ram 174 and the closure plate actuator 206.

While design of specific actuators employed may be varied as a matter of convenience, the actuators actually employed, excepting actuators 174 and 206, are of a spring-loaded type which include convenient pressure escape or relief valves connected therewith. Since actuators of this type are well known, a detailed description thereof is omitted in the interest of brevity.

Each of the valves 380 is connected with an electrically operated valve drive unit 382 adapted to be activated by a solenoid or the like connected therewithin. As it is intended that each of the valves 380 be driven through an associated unit 382 for directing fluid, preferably air, to the associated actuator, the valves are interconnected with a conveniently provided source of pressurized air, or tank 384, of any suitable design.

The manner in which the valves 380 are connected with the tank 384 is a matter of convenience, however, as schematically illustrated in FIG. 31, suitable pressure lines 386 are provided to extend between the tank 384 and the various valves 380. It should be understood that where hydraulic fluid is employed, convenient fluid conduits including suitable return lines, normally, are provided for recirculating the fluid from the various actuators to the tank. Furthermore, the system may be provided with convenient accumulators and system pumps as is found desirable.

As illustrated in FIG. 31, each of the valve drive means 382 directly is connected at one side thereof to one side of a D.C. (direct current) source of electrical energy, illustrated as a battery 388. The opposite side of the battery is connected to a system control input terminal 390 of a system control circuit 392.

In effect, the system control circuit 392 serves as a stepping switch for selectively and sequentially driving the various drive units 382 of the valves 380 in selected and appropriate sequence for achieving a selected actuation of the associated valve-connected actuators. Mounted within the control circuit 392 there is a continuous or circular bus bar 394 which is connected to the terminal 390 through a suitable input lead 396.

As each of the drive units 382 is connected to one side of the battery 388, it should readily be apparent that in order to achieve actuation of any of the valves 380, it only is necessary to complete an electrical circuit from the terminal 390, through the bus bar 394, to the selected unit 382 for activating the unit to achieve a valving sequence for the associated valve

380. Therefore, a plurality of suitable leads 397 are employed for connecting each of the drive units 382 to one of plurality of electrical contacts, designated A₁ through A₄, B₁ through B₄, and G₁ through G₄, located adjacent to the bus bar 394, whereby the drive units may be electrically connected with the bus bar at appropriate points in the machine's cycle to achieve a selected sequential and simultaneous operation of the associated actuators.

As illustrated in FIG. 2, a complete cycle of the machine represents 24 feet of machine travel. Further, a string of four buttons, applied on 3-foot centers followed by a 15-foot interval represents one machine cycle. Therefore, 360° of the circular bus bar represents one machine cycle or 24 feet of machine travel. As can be readily appreciated, the brush 32 is to be lowered only four times in a distance of 9 feet, while it is supported in a raised condition through a continuous distance of 15 feet for each cycle of machine operation assuming that no rectangular button is to be applied during the cycle. Therefore, the contacts B₁ through B₄ are arranged about the bus bar at a spacing of approximately 36° of rotational displacement. Hence, for each machine cycle, the brush rotor 262 is lowered at intervals of 3 feet as the drive unit 382 for the associated valve 380 sequentially is connected with the contacts B₁ through B₄.

As can readily be understood, four circular buttons must be delivered by the advance gate 116 for each complete cycle of operation of the machine. Therefore, the rocker arm 120 must be oscillated through four cycles for each cycle of operation of the machine. Hence, the plurality of electrical contacts G₁, G₂, G₃ and G₄ are disposed adjacent to the circular bus bar 394 and electrically connected with the drive unit 382 of the valve 380, as provided for the actuator 126. These contacts are connected with the bus bar 394 for sequentially activating the actuator 126 for pivotally driving the rocker arm 120 so that four circular buttons are caused to be delivered to the button ejector 150 within the first 9 feet of travel of each cycle of the machine.

Also, for each button applied to the surface of the highway, the button ejector and glue applicator simultaneously must be actuated. As can be readily seen from the illustration of FIG. 31, the plurality of contacts A₁ through A₄ also are disposed adjacent to the bus bar 394 so as to be sequentially connected with the bus bar 394 for driving the actuators 174 and 206 connected with the button ejector and glue applicator mechanism 150 and the closure plate 196. Therefore, the contacts sequentially are connected to a valve drive unit 382 associated with the actuators for controlling operations of the associated valve 380 of the actuators 174 and 206.

In each instance, the series of contacts are approximately 37° apart, however, this positioning may be varied as is found convenient. Furthermore, it will be noted that since the brush 32 is the first unit to be actuated, the contacts B₁ through B₄ are positioned slightly ahead of gate contacts G₁ through G₄, which are, in turn, arranged ahead of the contacts A₁ through A₄ of the advance gates. The natural consequence is that the actuators 174 and 206 are actuated subsequent to the operation of the advance gates which, in turn, are actuated subsequent to the operation of the brush 32 during each cycle of the machine. It is to be understood, however, that the relative positioning of the contacts is a matter of convenience and that the contacts may be displaced relative to the other contacts in any manner found suitable to achieve the desired simultaneous and/or sequential operation of the machine for each of its cycles.

In order to achieve the desired bridging between the contacts A₁ through A₄, B₁ through B₄, G₁ through G₄, and the bus bar 394, the system control circuit 392 is provided with a rotatably displaceable electrical bridge 398, FIG. 13, which is drivingly indexed about a vertical axis extending through the center of the circular bus bar 394.

The bridge 398 includes a horizontally extended rotating arm 400, so mounted as to be mechanically indexed by a drive shaft 402 and includes depending and electrically connected

contact brushes 404, 406 and 408. The contact 404 is mounted on the arm and disposed in sliding engagement with the circular bus bar 394 with the contacts 406 and 408 at opposite sides thereof so that the brushes 406 and 408 are continuously energized by the battery 388 through a circuit including the bus bar and the terminal 390. Therefore, as the shaft 402, FIGS. 13 and 30, is driven to rotate the arm 400, the electrical contacts B₁ through B₄ are engaged by the brush contact 408. As the brush contact sequentially engages contacts B₁ through B₄, an electrical signal is repetitiously applied to the drive unit 382 for the brush 32.

The brush contacts 406, likewise, are continuously energized through an engagement of the brush contact 404 with the bus bar 394 so that the electrical contacts G₁ through G₄ and A₁ through A₄ are sequentially energized as the arm 400 is indexed by the drive shaft 402. Consequently, the advance gate 116 is repeatedly actuated for delivering four circular buttons during each machine cycle.

Referring now to FIG. 2 in particular, it will be noted that midway between alternate "strings" of four circular buttons there is deposited a rectangular button. Since the rectangular buttons are delivered midway between the strings of circular buttons, preferably between alternate strings, it is necessary that the machine be provided with a system control circuit for accommodating application of the rectangular buttons at appropriate intervals.

As hereinbefore discussed, a complete cycle of operation of the machine occurs within 24 feet of travel for the machine. That is, starting with a first circular button, the machine will lay four circular buttons within 9 feet, followed by an interval of 15 feet, which occurs before completion of the machine's cycle. Since a rectangular button is delivered during alternate machine cycles, after the four circular buttons are delivered, and midway of the interval, the circular bus bar 394 is employed for driving the associated valve 380 for the brush 32 once during alternate cycles of the machine. Also, an advance gate contact G₅ is connected with a drive unit for actuating the advance gate 118 once for each alternate cycle of the machine and a final gate or applicator actuator contact A₅ is provided for actuating the drive unit 382, connected with the actuators 174 and 206, of the button ejector and glue applicator devices once during the final interval of each alternate cycle.

Since the electrical contacts B₅, G₅ and A₅ are sequentially arranged within the path of the brush contacts 406 and 408, as they depend from the arm 400, it might be expected that each of the associated actuators is operated once for each machine cycle for delivering from the machine a rectangular button. However, as aforementioned, it is intended that the machine deposit a rectangular button only between alternate strings of four circular buttons. Therefore, it is necessary that the circuit for operating the machine for delivering the rectangular buttons be interrupted between successive cycles of the machine, whereby the rectangular buttons are caused to be delivered between alternate strings of circular buttons.

This interruption is achieved by employing a cam-operated circuit interrupter gang switch 410 disposed between the system control circuit 392 and the drive units 382 for the various actuators employed for delivering and applying the rectangular buttons. The interrupter switch may be of any convenient design, however, as presently employed, the switch includes a plurality of parallel reeds supporting contacts AS, BS and GS which are spring biased to a normally open condition, but which may be deflected to a closed condition through the operation of an adjacently disposed cam 412.

As a practical matter, prior to the actuation of the ram 74, and the actuation of the advance gate 118 for the rectangular buttons, it is desirable that the brush 32 be driven for cleaning the surface of the highway midway between the strings of buttons. This actuation of the brush is achieved by connecting the electrical contact B₅ to a second drive unit 382, as provided for a second valve 380, operatively coupled to the actuator 308. This connection is achieved through the interrupter switch contact BS as they are so closed within the switch 410.

so that a circuit is completed from the circular bus bar 394 to the drive unit 382 for the second valve 380 provided for selectively driving the actuator 308.

As is illustrated in FIG. 31, the electrical contact G₅ is connected through a pair of normally open contacts GS, to a circuit output terminal 414. The terminal 414 is, in turn, electrically connected to the drive unit 382 for the actuator 126 of the advance gate 118 as well as the drive unit 382 for the actuator 80 of the rectangular button ejector 74. Therefore, only when the switch GS is closed is there a circuit completed through the interrupter circuit 410, between the electrical contact G₅ and the drive units 382 for the actuators 80 and 126 so that the ram 74 and rocker arm 120 are actuated.

The button ejection and adhesive application operations for applying the rectangular buttons delivered through the advance gate 118 likewise is achieved by electrically connecting the bus bar 394 with the drive unit 382 for the associated valve 380 operatively coupled with the actuators 174 and 206 of the button ejecting and adhesive applying mechanism. This connection is achieved through the contacts 404 and 406, serving to connect the electrical contact A₅ and the circular bus bar 394 in the same manner as heretofore described with respect to the electrical connection of electrical contacts A₁ through A₄. However, the contact A₅ also is connected to a drive unit 382 through the switch 410 at normally open contacts AS.

The switch 410 thus serves as an interrupter for the circuit between the contacts and the various drive units associated therewith so that the drive units can be energized only in the presence of closed switches AS, BS and GS. Since it is intended that the rectangular buttons be deposited only between alternate strings of circular buttons, it is intended that the switch 410 be closed for each alternate cycle of the machine. This alternation is achieved through an indexing of the associated cam 412 which includes a cam wheel having equally spaced cam lobes 416, FIG. 32, for sequentially engaging a cam follower 418. The cam follower 418, in turn, operatively is connected with the reeds of the switch in a convenient manner such that as the cam follower 418 is engaged or is caused to ride on a cam lobe 416, the contacts of AS, BS and GS of the switch 410 simultaneously are forced together or closed, and as the cam follower 418 is disengaged from the cam lobe 416, the contacts of the switch are urged to their normal switch-open condition.

Indexing of the cam 412 is achieved through the use of a convenient drive shaft 420 fixedly secured to the cam wheel 415 and rotatably supported within suitable supports 422. Indexing drive of the shaft 420 is achieved through a pawl and ratchet drive coupling 424 including a pawl 426 and a ratchet wheel 428 fixedly secured to the drive shaft 420.

In operation, the pawl 426 is advanced in engagement with the teeth of the ratchet wheel 428 for rotating the shaft 420 and thereby displacing the cam lobes 416 relative to the cam follower 418. The pawl 426 is, in turn, caused to advance the ratchet wheel through an energization of an electromagnet 430 having a suitable armature or plate 432 operatively coupled with the pawl 426 in any convenient manner.

While not shown, it is to be understood that the armature 432 is spring biased, by a suitable biasing means so as continuously to urge the plate in displacement in a direction away from the core of the electromagnet, whereby, as the electromagnet is electrically energized, the armature 432 is attracted in displacement towards the core of the magnet. When the electromagnet is deenergized, the armature 432 is displaced away from the core under the influence of the associated biasing means. Therefore, through a pulsing energization of the electromagnet 430, repetitive displacement of the pawl 426 is achieved so that the pawl serves to advance or thus index the shaft 420, in a series of steps, each time the electromagnet is pulsed.

Since the switch 410 is closed for completing a circuit from the bus bar 394 to the various actuators provided for applying the rectangular buttons during alternate cycles of the machine, it is to be understood that the cam 412 is indexed

once for each cycle so that during one cycle of machine operation a cam follower 416 is out of engagement of a cam lobe, for effecting an opening of the contacts of the switch 410, while on the next or following cycle a cam lobe 416 is advanced into driving engagement with the follower 418 for thereby closing the switch contacts.

To achieve the desired energization of the electromagnet 430, an electrical contact 434 is disposed within the path of the depending contact brush 406 at a point ahead of the contacts B₅, G₅ and A₅ so that the switch 410 is selectively conditioned prior to the electrical coupling of the circular bus bar 394 with the electrical contacts B₅, G₅ and A₅.

If the switch 410 is open, during a given machine cycle, no rectangular buttons will be applied during that cycle, due to the open circuit at the switch 410, however, if the electromagnet 430 is pulsed for indexing the cam lobe 416 into engagement with the cam follower 418, energization of the associated actuators connected with the electrical contacts B₅, G₅ and A₅ sequentially is achieved for effecting a delivery and application of a rectangular button.

While not mandatory, for purposes of timing it may be found desirable to provide means for adjusting the position of the electrical contacts B₁ through B₅ for the brush 32, relative to the remaining electrical contacts of the circuit 392. This is achieved simply by mounting the contacts for the brush 32 on a bearing supported plate 436, FIG. 13, which is supported for rotation by conveniently mounted bearings 438, relative to an outer ring 440 which serves to support the remaining electrical contacts of the circuit. Relative adjustment between the plate 436 and the outer ring is achieved through a convenient screw-threaded coupling 442 secured to the plate 436 through a coupling arm 444. The position of the arm 444 is altered through a selected rotation of a screw-threaded drive shaft 446, FIG. 29, operatively coupled with the screw-threaded coupling 442.

A convenient knob 448 is secured to one end of the shaft 446 so that the shaft may be rotated in opposite directions for reversing directions of travel of the arm 444, whereby selectively positioning of the plate 436, relative to the outer ring 440, and consequently the relative positions for the electrical contacts of the circuit are varied for altering the timing of the operation of the actuators for the brush 32 relative to the operation of the remaining actuators.

MACHINE CONTROL DRIVE SYSTEM

In order to achieve an indexing rotation of the arm 400, the shaft 402 intermittently is rotated through a pawl and ratchet drive mechanism 448. This mechanism includes a ratchet wheel 450 and a spring-biased pawl 452 having a suitable protrusion or lip 453 arranged thereon, FIG. 30. The pawl 452 is pivotally connected to an oscillating arm 454, at a convenient pivot 455, which is pivotally supported at a pivot 456 and fixedly secured to a cam follower arm 458. The arms 454 and 458, in effect, define a bellcrank 459 which supports a convenient cam follower 460 connected at its distal end. The thus formed bellcrank operatively is oscillated about the pivot 456 for imparting reciprocation to the pawl 452. In practice, the bellcrank is cam-driven in a first direction and return-driven in a reverse direction by a drive link including a tension spring 461.

As presently employed, the bellcrank 459 is driven in a first direction for extending the pawl lip 453 into engagement with the next-in-line or successive-in-line teeth of the ratchet wheel, while the spring 461 applied the force required in indexing the shaft 402 to advance the arm 400 to its next position. Of course, it is entirely possible to reverse the operation so that the indexing is positively achieved by a cam driving displacement of the bellcrank while the spring 461 is employed to return the lip 453 of the pawl 452 to engage the next-in-line teeth of the ratchet wheel.

In order to achieve displacement of the pawl 452 through a cam driving operation, the cam follower 460 is disposed

within a path of a series of cam lobes 462 mounted at selected intervals on a cam plate 464, along the periphery thereof. The plate 464 conveniently is coupled with one of the wheels 250 in a manner such as to be driven thereby. Any suitable means, such as in the interlocking collar 466, FIG. 36, may be employed for coupling the plate 464 with one of the adjacent wheels 250.

Therefore, it will be appreciated that as the plate 464 is rotated, the cam lobes 462 serially are advanced in response to a driving displacement of the wheels 250 as they are advanced along the surface of the highway. Displacement of the cam lobes 462 serves to cause the cam follower 460 to engage the lobes and effect an oscillatory displacement of the bellcrank 459 about the pivot 456. As the cam lobes disengage the cam follower, the spring 461 urges the bellcrank in a reversed direction of rotation about the pivot 456 so that the lip 453 of the pawl 452 engages and imparts displacement to the teeth of the ratchet wheel thereby to advance the arm 400 through one intermittent step of rotation.

To control the throw of the arm 454 for the pawl 452, a suitable screw-threaded pin 468 may be mounted in a support adjacent to the arm 455 and serve as an adjustable screw-threaded stop for adjusting the extent of displacement of the arm 458 relative to the pivot 456 so that the extent of pawl displacement for the pawl is achieved for thereby controlling the extent of rotation imparted to the arm 406 at each advancement thereof.

It frequently is desirable to inactivate the operation of the machine as the frame thereof is driven along the highway for delivery, as well as for other purposes. This is achieved through a convenient camming mechanism 469 coupled with the bellcrank 459, as illustrated in FIG. 30. The bellcrank includes an elongated camming arm 470 extended therefrom which, in effect, serves as a cam lever, whereby foreces applied thereto serve to rotate the bellcrank about its pivot 456. Rotation of the arm is achieved through an engagement therewith of a camming surface 472 formed on an eccentric cam member 474 mounted to pivot about a cam pivot 476 conveniently arranged adjacent to the arm 470. As the eccentric cam 474 is pivotally rotated about the pivot 476, the surface 472 thereof engages the surface of the arm 470 and forcibly displaces the arm in a direction such that the bellcrank 459 is displaced about its pivot 456 in a direction such that the cam follower 460 is withdrawn from the path of the series of cam lobes on the plate 464. If desired, the adjustment stop 468 also may be advanced for securing the arms 454 and 458 in an inoperative position relative to the cam plate 464.

In order to achieve the desired rotation of the eccentric 472 a push-pull linkage 478 conveniently is mounted within the frame structure for the control system and connected within the eccentric. The linkage is reciprocated by any suitable means including a convenient handle-lever 480, of common design, connected at one end thereof and adapted to actuate the linkage in a reciprocating manner.

In order to assure that the ratchet wheel 450 does not encounter backlash, a spring-biased latching pawl 482, having a teeth engaging lip 483 is pivotally supported adjacent to the ratchet wheel 450 by a suitable pivot 484, FIG. 30. As a practical matter, the pawls 452 and 482 may be spring biased into engagement with the surface of the ratchet wheel employing a common tension spring 486 coupled therebetween by convenient protrusions formed to extend from the pawls. Hence, the spring 486 continuously and simultaneously urges both pawls into engagement with the teeth of the ratchet wheel 450. Therefore, as the bellcrank 459 causes the pawl 452 to reciprocate, the latching pawl 482 remains engaged with the teeth of the ratchet wheel and as the ratchet wheel 450 is indexed by the pawl 452 acting under influence of the spring 486, the pawl 482 is disengaged and caused to drop into adjacent detents of the next-in-line teeth of the ratchet wheel.

Therefore, it should be understood that the shaft 402 serves intermittently to advance the arm 400 relative to the electrical contacts of the circuit 392 as the cams 462 engage the cam

follower 460. The rate at which the arm 400 is stepped or indexed is directly dependent upon the rate of displacement of the ratchet teeth 450 and the spacing of the cams 462, as well as the rate of rotation of the cam plate 464. Therefore, the rate of rotation for the arm 400 may be varied as required by varying the setting of the stop 468 as well as by altering the design of the ratchet wheel 450 and the cam plate 464.

MACHINE ADJUSTMENT

In some instances, such as for purposes of adjustment, it may be convenient to observe the location of the arm 400 relative to the various electrical contacts mounted on the plate 436 and its associated ring 440. This is accommodated simply by providing a pointer 488 drivingly coupled with the shaft 402 in any suitable manner. The pointer 488 is particularly useful in adjusting the positioning of the contacts through the adjusting rotation of the knob 448. Hence, it is to be understood that the pointer 488 is driven in rotation with the arm 400 and serves to indicate, at any given time, the extent of completion for each cycle of the machine.

In adjusting the timing and operation of the machine, it may be found to be particularly desirable to adjust the positioning of the tire 236 relative to the gate 136 of the button ejector 150. Therefore, in practice, the frame 240 and axle 238 are coupled through a suitable bearing structure 490, including a bearing block 491, to the frame of the vehicle by conveniently arranged and supported screw-threaded couplings 492. These couplings are of any suitable design and are adapted to be rotated by a screw-threaded drive shaft 494 having a convenient "T" handle 496 connected therewith. As illustrated in FIG. 7 and 13, a bearing structure and handle 496 are provided at each side of the frame 240, whereby the tire 263 and the wheels 250 may be advanced towards or retracted from the ejector mechanism of the button ejector 150 for purposes of adjusting the machine's operation.

Furthermore, as a matter of convenience, in adjusting the machine's operation, the actuator 254 is actuated or driven by any suitable device operatively connected to a convenient pressure system such as the tank 384. Also, while not shown, it has been found particularly desirable to provide suitable circuit switch means located on the machine at convenient locations, whereby selected circuit controlled mechanisms may be selectively actuated as circuits are completed thereby between both sides of the battery 388 and the various drive units 382 for the valves 380 in any convenient manner.

MODIFIED MAGAZINE

In certain instances, it is found advisable to provide the magazine 34 with a magazine subsection 501, FIGS. 33 and 34, which varies substantially from the receptacle 49 of magazine subsection 34. While the belt actuated receptacle 49 for delivering the circular buttons functions quite satisfactorily for most purposes, it is possible to achieve a more accurate control for the button feed by providing a "Lazy-Susan" magazine arrangement wherein the circular buttons are arranged in vertical stacks and delivered one at a time from the lowermost portions thereof, in a manner quite similar to that heretofore disclosed with respect to the rectangular buttons.

It is to be noted that the Lazy-Susan subsection 501 includes a plurality of rotatable hoppers 502, mounted for rotation about a vertical axis extending through a central supporting bearing 504. Each of the hoppers includes a plurality of vertically disposed, contiguous channels 506 adapted to be filled from the top. The channels are interconnected through radially extended supports 508 coupled with the bearing structure 504. The channels are so dimensioned as to retain therein the buttons against lateral displacement, however, the lowermost end of the outer periphery of each of the channels includes an opening 509 having a dimension sufficient to accommodate lateral passage of one button at any given time.

It is understood that a suitable supporting structure, such as an annular retainer 510 circumscribes the lowermost por-

tion of the hopper 502 so that each opening 509 is closed at all stations other than a button discharge station adjacent to the throat of a button discharge chute 512.

Mounted for laterally directed rectilinear reciprocation adjacent to the subsection 501 there is a discharge ram 514. The ram is driven through a suitable link 516 connected with and adapted to be actuated by a pneumatic actuator 518 in a manner similar to that employed for the actuation of the ram 74. The ram operatively is inserted through the adjacent channel 506 and extended toward the chute 512 for discharging the buttons from the channels 506 into the chute 512.

In practice, a plurality of hoppers 502 may be employed, with each of the hoppers being provided with convenient indentations 520 into which spring-loaded lug 522 is inserted for retaining the hopper at desired positions relative to the throat of an adjacent discharge chute 512. As each vertical channel 506 is emptied, through a sequential operation of the ram 514, the hopper is indexed one step so that the spring-loaded lug 522 is caused to engage the next-in-line indentation for retaining the hopper in a fixed position with respect to the discharge chutes 512. Hence, it will be understood that the channels 506 of the Lazy-Susan hopper 502 may be filled with stacks of circular buttons and indexed to the chute 512 for sequentially delivering the buttons of the stacks of buttons retained in the channels. While two Lazy-Susan hoppers are illustrated, it should be apparent that as many hoppers as are found desirable may be employed.

Furthermore, and of particular importance, where the Lazy-Susan hopper is employed, the advance gate 116 of the gating section 40 may be eliminated, since the buttons are sequentially discharged at appropriate intervals through the actuation of the ram 514.

The actuator 518 is coupled to the pressurized source 384 of fluid through a convenient valve and drive unit, not shown, and operated by the system control circuit 392 in a manner similar to the operation of the actuator for the ram 74. The control circuit is so timed that at any appropriate interval in each cycle of the machine's operation, the actuator 518 drives the link 516 for advancing the ram 514 along its preselected path for engaging the periphery and discharging the lowermost circular button through the opening 509 of the channel 506 as it is positioned adjacent the discharge chute 512.

As the stack of buttons for each of the channels 506 is depleted, the hopper 502 is rotated or indexed to its next position and held in place through an engagement of the lug 522 with the indentation 520. The buttons again are delivered by the reciprocating ram 514 until the hopper eventually is depleted. In instances where multiple hoppers are employed, the adjacent hopper is activated through closure of the suitable electrical switch, not shown, for permitting the ram of that hopper to discharge buttons through the adjacent throat of the discharge chute 512.

MODIFIED ADHESIVE APPLICATOR

In some instances, modified adhesive applicators have been found particularly desirable to employ a reciprocating adhesive applicator whereby the applicator is positioned relative to the surface of the highway in a manner such that the nozzle thereof is displaced rearwardly at the same rate in which the vehicle is moving forwardly so that the nozzle of the applicator remains fixed relative to the surface of the road until discharge of the glob of adhesive is completed.

As illustrated in FIGS. 35 and 36, a modified rectilinearly reciprocating applicator 523, including an adhesive discharge nozzle 524, is mounted on a suitable reciprocating frame 526. The frame, in turn, is supported by means including convenient casters 528 pinned or otherwise coupled with the frame and seated in an elongated track 530, which is of a length sufficient to accommodate discharge of a glob of adhesive from the nozzle 524. The track operatively is secured to the frame member 240 of the vehicle at a point beneath the

gated track 38 by convenient structure, including vertical stringers 532.

In order to achieve the desired reciprocation of the frame 526, a double-acting pneumatic actuator 534 operatively is coupled to the frame and is driven through a valve 380 controlled for sequential operation by the system control circuit 392 in a manner similar to that aforescribed with respect to the various operating mechanisms of the machine. The shaft of the actuator 534 is coupled through a suitable connector 536 provided on the frame by any convenient coupling such as screw-threaded nuts 538. Therefore, it will be appreciated that the frame 526 may be reciprocated in a direction opposite to the direction of travel of the machine at a rate commensurate therewith, in response to a controlled actuation of the actuator 534, which serves to drive the frame rearwardly along the track 530 as the nozzle discharges the adhesive. At the termination of the adhesive discharge, the nozzle is returned to its starting position through the operation of the valve for reversing the pressurization of the actuator.

The nozzle 524 is of any suitable design such as a commercially available mixing motor 540 having an inlet at the opposite sides thereof, for accommodating a delivery of epoxy material thereto. While various mixing motors may be employed, the type presently utilized includes "proportioners" 544 having piston shafts 545 extended therefrom and driven by an air-ram shaft 546 connected thereto through suitable couplings 548. The motor 540 includes a reversely driven auger which mixes the epoxy and the "hardener" as it is delivered thereto from the proportioners 544. However, upon reciprocation of the shaft 546, the shafts 545 are downwardly displaced for displacing the piston heads within the barrels of the proportioners 544 whereby the epoxy, and its hardener, is delivered into the mixing motor 540. As the epoxy and hardener are delivered from the proportioners 544 a glob of mixed adhesive is forced from the motor and caused to be delivered from the nozzle 524 to the surface of the highway.

The duration of the delivery operation is directly related to the duration of the travel time provided for the shafts 545. Therefore, by varying the rate at which the air-ram shaft 546 is displaced the rate at which adhesive is delivered from the nozzle 524 readily is varied.

In instances where the applicator 523, FIGS. 35 and 36, is being employed, it is to be understood that the control circuit 392 is provided with suitable electrical contacts for selectively achieving an activation of the pneumatic actuator 534 at appropriate intervals so that the nozzle 524 remains fixed relative to the surface of the highway for a determinable period as the vehicle is advanced therealong, whereby "stringing" of the adhesive is effectively prohibited.

In practice, it has been found relatively simple to adjust the timing of the ejector mechanism 150 with the discharge of adhesive through the nozzle 524. The adjustment is achieved simply by positioning the circuit contacts employed in activating the actuator 534 at appropriate locations ahead of contacts A₁ through A₅. If desired, a pair of elevating rams 550 can be coupled with parallel links 552 and operated in any convenient manner for elevating the applicator.

OPERATION

The operation of the described embodiment of the subject invention is believed to be clearly apparent and is briefly summarized at this point.

Assuming that the magazine subsections 34 and 36 of the magazine section 30 have been appropriately filled with buttons to be applied to the surface of a highway, the adhesive pots 22 are filled with an appropriate adhesive material, the boom 374 is attached at the clevis 375 to the leading end of the vehicle, the cam 460 of the machine control system drive is positioned relative to the cam wheel 464, the pivoted frame 240 is in an operative position, and the machine control system seated at its initial or starting position; the machine is in condition to be operated.

An operator, located at the power and steering section 10 of the vehicle, now causes the power plant of the vehicle to become activated. The vehicle is advanced in a manner such that the caste supported frame 374 is aligned on the lane-divider line of the highway.

As the vehicle advances, circular buttons are delivered from the magazine subsection 34 along the gated track 38 and the arm 400 is indexed through a displacement of the cam 460 of the bellcrank 469. As the arm 400 is indexed, the depending contact 404 continuously is maintained in electrical contact with the bus bar 394. At the first station to which the arm 400 is indexed by actuation of the machine control drive the contact 408 depending from the arm 400 engages the first-in-line contact B, whereupon the valve 380 is actuated, through the associated drive unit 382, causing the actuator 308 to drive the brush rotor 262 of the brush 32 into engagement with the surface of the highway, whereupon the discs 264 engage the surface and rapidly remove foreign material therefrom as rotation is imparted to the rotor. This rotation is imparted to the rotor in response to a driving rotation of the drive shaft 300 acting through the gear train which includes the gear box 296, the sheaves 270 and 274 and V-belts 268.

At the next indexing of the arm 400, the pressure is relieved through the valve 380 permitting the spring of the actuator 308 to cause the rotor 262 to disengage the surface of the highway so that a first surface area is provided to receive adhesive.

At the next indexing step of the arm 400, an advance gate contact G₁ is caused to be electrically connected with the bus bar of the circuit 392 so that the advance gate 116 is activated for a circular button to the button ejector mechanism 150. At the next step of the arm 400, the brush 32 is again brought into engagement with the surface of the highway for cleaning a selected area to receive a glob of adhesive.

The next step of the arm 400 brings the contact 406 into engagement with the contact G₂ whereupon the gate 116 is again activated so that a second button now is released to be delivered to the button ejector before the first button is delivered, so that a second button is readied for the final gate. Due to the rate of ejection, the first button will be ejected before the second button arrives.

At the next step of the arm 400, the brush contact B₃ is again contacted by the brush contact 408 for again causing the brush 32 to engage and clean a selected surface area of the highway, at the same time the contact 406 engages the contact A₁ which serves to activate the actuators 174 and 206 of the button ejector and adhesive applicator mechanism so that the adhesive applicator is caused to deliver a glob of adhesive and the button ejector is caused to eject the button previously delivered thereto in response to the actuation of the gate 116.

The arm 400 is again indexed causing the gate 116 to again be activated for again delivering a circular button to the button ejector mechanism 150, this actuation is, in turn, followed by an actuation of the brush 32 and a second activation of the actuators 174 and 206 for delivering a second glob of adhesive and button to the surface of the highway.

The next step of the arm 400 causes the gate 116 again to deliver another button along its way to the button ejector mechanism 150. Since the contacts are connected with an open circuit, due to an energization of contact 434 and switch 410, this engagement is ineffective.

The brush 32 is activated four times for cleaning four selected areas on the surface of the highway and is not activated again during the remaining portion of the cycle of the machine. The arm 400, however, is indexed in steps through contacts A₃ and A₄ for causing the remaining buttons to be delivered by button ejectors to the surface of the highway.

During the first cycle of operation for the machine as it is advanced along the surface of the highway, no rectangular button is delivered, due to the required 15-foot interval, so that the machine is permitted to complete this cycle of operation while laying four circular buttons on 3-foot centers, as illustrated in FIG. 2.

During the following cycle of the machine, the contacts B₁ through B₄ and G₁ through G₄ and A₁ through A₄ are again contacted by the depending brush contacts 406 and 408 of the indexing arm 400 to drive the machine components, as aforescribed. However, since it is necessary to deliver and apply a rectangular button to the surface of the highway, during this cycle of operation, as the brush contact 406 is brought into contact with the contact 434, connected with the electromagnet 430 of the circuit 410, the cam wheel 412 is indexed bringing the cam lobe 416 into engagement with the cam follower 418 for depressing the reeds and closing the normally open contacts GS, BS and AS. Continued indexing of the arm 400 again brings the contact 408 into engagement with the brush contact B₅ whereupon a circuit is completed between the bus bar 394, through the circuit 410, to a valve 380 connected with the actuator 308 of the brush 32 so that the rotor 262 is caused to engage the surface of the highway and remove the foreign material therefrom.

The next advancement of the arm 400 causes the contact 406 to engage the contact G₅ which serves to connect the bus bar 394 to the actuator 126 of the gate 118 for delivering to the ejector mechanism 150 a rectangular button while at the same time causing the ram 74 to be driven through the chamber 72 of the magazine subsection 36 for delivering another through the gated track to the gate 118 whereat the button is intercepted and retained for subsequent delivery during a subsequent cycle of the machine.

As the machine advances along the surface, the buttons are serially delivered by the button ejector mechanism 150 while the tire 236 serves to engage the upper surface thereof for seating the buttons positively in the globs of delivered adhesive applied by the adhesive applicator 176.

Furthermore, in instances where the machine is being employed to deliver buttons to a surface having gentle curves, the brush is arcuately displaced in a horizontal direction about the pivot point 290 through an operation of the push-pull linkage 366. It is important to note, however, in instance where the curves encountered are rather sharp, or for any other reason, the boom may be disconnected at the clevis 376 and the housing 280 of the brush fixed relative to the bracket 284 by screw-threaded studs 292. The machine then functions as aforescribed without the booms.

As the machine continues along the surface of the highway, the cycles are repeated in pairs of cycles with four circular buttons being applied during a first cycle, followed by four circular buttons and a rectangular button during the second cycle. Since the operation for each mechanism of the machine has heretofore been provided in conjunction with the description of the mechanism, a detailed description of the operation thereof is omitted at this point in the interest of brevity.

In view of the foregoing, it should be readily apparent that the present invention provides an automated lane-divider button applying machine particularly suited for use in applying lane-divider buttons at selected intervals along lane-divider lines of surfaced highways, and includes a fully automated system for cleaning selected areas, depositing globs of adhesive in the cleaned areas and applying circular and rectangular buttons, in predetermined order, in the applied adhesive.

Although the invention has been herein shown and described in what is conceived to be the most practical and preferred embodiment, it is recognized that departures may be made therefrom within the scope of the invention.

Having described by invention, what I claim as new and desire to secure by Letters Patent is:

1. An automated lane-divider button applying machine adapted to apply lane-divider buttons to selectively spaced areas of given surfaces, comprising:

- A. means adapted operatively to remove foreign matter from spaced areas of a given surface;
- B. adhesive applicator means for depositing a predetermined quantity of adhesive at each of the selected areas;
- C. button applicator means for delivering and seating lane-divider buttons within the deposited adhesive; and

D. a mobile frame operatively supporting said means for displacement relatively to the spaced areas.

2. An automated lane-divider button applying machine, comprising:

- A. a mobile frame;
- B. a prime mover associated with the frame for driving said frame along a selected path of travel and over a surface;
- C. a steering mechanism for controlling directions of travel for said frame;
- D. a button depositing system mounted on said frame including,

- 1. means defining a surface cleaner for cleaning areas of a button receiving surface;
- 2. means defining an adhesive applicator for applying globs of adhesive to the cleaned areas; and
- 3. means defining a button applicator for applying buttons to the applied globs of adhesive; and

E. machine control and sequencing means including pneumatic actuators adapted to activate the surface cleaner, the adhesive applicator and the button applicator in a preselected sequence, whereby the machine is activated sequentially to clean surface areas for receiving globs of adhesive, to apply globs of adhesive to the areas and to apply buttons to the applied globs of adhesive.

3. The machine of claim 2 wherein the machine control and sequencing means includes a plurality of electrically activated pneumatic actuator control valve drive units and an electrical control circuit connected with the units adapted to couple the units with a source of electrical energy for achieving a selected actuation of the actuators for thereby imparting to the machine sequenced operations.

4. The machine of claim 3 wherein the timer includes:

- A. a driven rotor arm having a plurality of interconnected electrical contact brushes depending therefrom;
- B. circuit means continuously connecting a source of electrical energy to said brushes;
- C. a plurality of electrical contacts disposed within the path of the brushes adapted sequentially to be engaged thereby;
- D. electrical leads electrically connecting said contacts with said motors, whereby the motors are caused to be energized as the contact brushes are caused to engage the contacts; and

E. drive means adapted to rotate the rotor arm at selected rates or rotation, whereby the hydraulic motors are sequentially and selectively connected with a source of electrical energy as the rotor arm is caused to be rotated by the drive means.

5. The machine of claim 4 wherein the rotor drive means includes:

- A. a wheel disposed in operative engagement with the given surface and adapted to be driven in rotation thereby;
- B. a cam plate operatively coupled with said wheel and adapted to be driven in rotation thereby; and
- C. a cam-driven indexing drive linkage coupled between the rotor arm and the cam plate for indexing the rotor arm at predetermined intervals of wheel rotation.

6. An automated lane-divider button applying machine adapted to be driven and sequentially operated for applying lane-divider buttons of the type including a supporting planar surface and an upper light-reflecting surface at predetermined intervals along the surface of a highway for thereby delineating highway traffic lanes, comprising:

- A. mobilized vehicle, including a steering mechanism and a prime mover adapted to be controlled by an operator for directing the machine along a given path above a selected surface of a given highway;
- B. a surface cleaner mounted on the vehicle and adapted to remove foreign material from selected areas of the surface;
- C. an adhesive applicator mounted on the machine adapted to apply globs of adhesive at each of the selected areas from which foreign matter has been removed;

- D. means defining a button magazine mounted on the vehicle and including a button delivery means adapted to eject lane-divider buttons from the magazine;
- E. button orienting means mounted adjacent the magazine adapted to receive and to orient buttons ejected by the button delivery means to direct the buttons along a given path through the machine;
- F. a button applicator arranged adjacent said orienting means adapted to receive and to deposit the oriented buttons in the globs of applied adhesive; and
- G. a pressure applicator for applying pressure to each of the buttons as it is deposited in a glob of adhesive, whereby the buttons are thus caused to be affixed to the surface at the select areas.
- 7. The machine of claim 6 further comprising gate means associated with the button orienting means adapted to intercept the buttons as they are directed along the path and to dictate the rate at which buttons are received by the button applicator.

8. The machine of claim 7 wherein the gate means includes a pivoted rocker arm having spaced stop-lugs and adapted to be pivotally actuated for alternately positioning the stop-lugs within a button arresting disposition within the path of the buttons to serially arrest and sequentially discharge the buttons as they are delivered thereto, and drive means operatively connected with the rocker arm adapted to actuate the rocker arm at selected intervals.

9. The machine of claim 6 wherein the means defining the button magazine further includes a plurality of vertical chutes for retaining the buttons in stacked, vertical alignment arranged in operative association with the button delivery means.

10. The machine of claim 9 wherein the means defining the button magazine further includes a chute indexing means connected with the chute for aligning the chute and the button delivery means.

11. The machine of claim 6 wherein the button magazine means further includes a closed, vertical wall defining a button receptacle having means defining therein a discharge opening for discharging buttons therethrough, and the button delivery means comprises:

- A. a horizontally disposed conveyor belt mounted within the receptacle and extending to said discharge opening, adapted continuously to displace buttons toward the discharge opening;
- B. a vertically disposed agitator belt operatively arranged adjacent the discharge opening of said receptacle and having an operative surface spaced from said horizontally disposed conveyor belt a distance sufficient for accommodating a serial passage of the buttons between the surfaces thereof; and
- C. drive means continuously driving the agitator belt in a manner such that its operative surface continuously is displaced upwardly, whereby randomly deposited buttons within the receptacle are continuously agitated and ejected in an ordered fashion from the discharge opening of the button magazine.

12. The machine of claim 11 wherein the means defining the button magazine means further includes a button dispenser adapted to receive and dispense buttons, comprising:

- A. a plurality of adjacent, vertically disposed channular chutes, each chute being adapted to receive and support therein a stack of buttons to be dispensed;
- B. indexing means connected with the chutes adapted selectively to advance the chutes to a button ejecting position; and
- C. a button ejector operatively associated with the chutes adapted selectively to discharge buttons therefrom.

13. The machine of claim 12 wherein the buttons delivered from the button receptacle are of a circular configuration having a convex upper surface and the buttons discharged from the channular track are of a rectangular configuration having an inclined light-reflecting planar side surface.

14. The machine of claim 6 wherein the button orienting means includes a pair of parallel and inclined tracks, one of which is provided with a button receiver having a substantially vertically aligned V-shaped channel section terminating in a substantially horizontally aligned terminal section, whereby the orienting means is adapted to support the buttons on a side edge surface within the V-shaped channel section, as the buttons are delivered from the magazine, and to reorient the buttons to a selected orientation in which the buttons are supported by the supporting planar surface as the buttons are directed along the path to the button applicator.

15. The machine of claim 14 further comprising a knife edge disposed within the button receiver adapted to engage the buttons while they are supported on an edge surface and to incline each of said buttons in a direction determined by the relative orientation of its supporting planar surface, whereby each button is caused to be inclined within the V-shaped section of a channel in a direction such that its planar surface is engaged and supported by one side surface of a V-shaped channel section.

16. The machine of claim 15 further including means disposed adjacent the V-shaped section adapted to engage each button and cause it to be oriented in a manner such that its planar surface is directed downwardly as it is advanced toward the terminal section of the track.

17. The machine of claim 16 further including a gate having a pivoted rocker arm and drive means operatively connected therewith adapted to alternately position opposite ends of said rocker arm into a button arresting disposition within the path of the buttons and sequentially to discharge the buttons as they are serially advanced into engagement with the opposite ends of the rocker arm.

18. The combination of claim 17 further including means adapted to insure that the buttons are advanced along the tracks in single file and in a common inclined plane, whereby a serial and ordered delivery of the buttons to the gate is accommodated.

19. The machine of claim 6 wherein the adhesive applicator comprises:

- A. a pair of mutually parallel tracks mounted on the vehicle adjacent the button applicator in parallel relation to the surface of the highway;
- B. a carriage supported for rectilinear reciprocation along said tracks;
- C. an adhesive nozzle mounted on said carriage adapted to discharge adhesive; and
- D. drive means coupled with the carriage adapted to drive the carriage in a first direction opposite to the direction of travel of the machine as adhesive is discharged from the nozzle and at a rate commensurate with the travel of said machine, and to drive the carriage in the direction of travel of the machine at a rate substantially greater than the rate of travel of the machine upon termination of adhesive discharge, whereby the nozzle is caused to be retained in a fixed relationship relative to each area as the adhesive is discharged from the nozzle as the machine continuously is directed along the surface of the highway.

20. The machine according to claim 6 wherein the adhesive applicator includes:

- A. a nozzle for discharging adhesive therefrom;
- B. means defining a pressure chamber operatively coupled with the nozzle and adapted to be supplied with a flowable adhesive; and
- C. a reciprocating discharge plunger mounted for displacement within the chamber for effecting a discharge of adhesive therefrom, whereby adhesive is discharged under pressure from the nozzle through an operative reciprocation of the plunger.

21. The machine of claim 20 wherein the adhesive applicator further includes a reciprocating member forming a reciprocating closure for said nozzle adapted to open and close the nozzle as the discharge plunger is reciprocatingly displaced for intermittently discharging adhesive from the chamber.

22. The machine of claim 21 wherein the reciprocating closure for said nozzle includes an actuator having a pivoted overcenter linkage adapted to be displaced to an overcenter position for imparting rapid reciprocation to said closure member, and linkage means adapted to delay rapid opening of the nozzle during a selected portion of the actuation of the actuator until an overcenter condition for the overcenter linkage is achieved.

23. The machine of claim 22 wherein the overcenter linkage includes a rectilinearly reciprocating spring-biased bellcrank adapted to be displaced by the actuator and operatively connected with the linkage means, whereby the overcenter condition is achieved by reciprocating the bellcrank to a predetermined point along its path of rectilinear travel.

24. A glue applicator comprising:

- A. a closed chamber having an inlet for delivering fluid adhesive thereto;
- B. a piston operatively disposed within one end of said chamber adapted to be displaced therethrough;
- C. means defining a discharge orifice at the opposite end of said chamber;
- D. a reciprocating closure member operatively seated in said discharge orifice adapted to be reciprocally displaced for effecting opening and closing of said chamber;
- E. a pneumatically driven ram connected with said piston adapted to impart axial displacement to said piston for forcing adhesive towards said orifice to achieve a pressurization thereof;
- F. linkage means connected with said reciprocating closure member;
- G. an overcenter drive means including a rectilinearly reciprocating spring-biased bellcrank connected with the linkage means for driving said closure member to displace the member from said orifice as the bellcrank is reciprocated; and
- H. an actuator connected with the bellcrank adapted to impart rectilinear reciprocation thereto.

25. An adhesive applicator comprising:

- A. an elongated barrel;
- B. means for delivering adhesive to the barrel;
- C. means defining an adhesive discharge port in a plane extending diagonally from the axis of the barrel;
- D. a reciprocating closure plate adapted to be displaced along a path having an axis extending transversely of the discharge port for effecting a selective opening and closing of the port; and
- E. a reciprocating, plate-coupled drive means for reciprocatingly displacing said plate including,
  - 1. means defining a bearing means fixed to the plate;
  - 2. a rectilinearly reciprocating drive link adapted to be driven along a path having an axis intersecting the axis of the path of the plate;
  - 3. an elongated lever pivotally connected at one end to the drive link;
  - 4. means defining a pivot bearing fixed to the lever between the ends thereof and adapted to support the lever for achieving an oscillation thereof as the drive link is reciprocated; and
  - 5. an abaxial pin means seated in the bearing means and including supported ends coupled with the elongated lever for effecting reciprocation of the plate as the drive link is reciprocated; the elongated lever is oscillated in response thereto.

26. The machine of claim 6 wherein the button applicator includes:

- A. a spring-biased stop for arresting each button as it is received therein;
- B. a button ejector having a spring-biased lip adapted to be actuated to engage the trailing edge of each button arrested by the stop and to eject the engaged button from the machine; and
- C. means mounting the button ejector in operative association with the adhesive applicator in a manner such that as

the button is ejected from the machine it is caused to be deposited in adhesive applied by said applicator.

27. The machine of claim 26 further including a resilient roller adapted to engage the upper surface of each of the buttons as it is deposited in the adhesive for forcibly seating the button within the adhesive.

28. The machine of claim 6 wherein the surface cleaner comprises:

- A. a driven rotary brush having a rotor including a plurality of rotatable discs connected thereto and adapted to strike the surface of the highway; and
- B. a pivotally supported frame supporting said brush for pivotal oscillation about a horizontal axis.

29. The machine of claim 28 further comprising drive means including a driven sheave and V-belt drive linkage mounted on the frame and operatively coupled with the rotor for imparting a determinable rate of rotation thereto.

30. The machine of claim 29 further including means operatively associated with said frame adapted to be actuated for pivotally oscillating said brush relative to the surface of the highway.

31. The machine of claim 30 further comprising a displaceable bearing mount supporting said brush for pivotal displacement about a vertical axis and displacement means adapted to impart lateral displacement of said brush whereby the brush selectively is displaced in lateral directions relative to the center line of said vehicle.

32. The machine of claim 31 further comprising guide means including:

- A. a boom pivotally connected at the leading end of the machine including support means engaging the surface of the highway and adapted to support the boom at its extended end;
- B. means interconnecting the steering mechanism of the vehicle with the boom whereby steereage of the boom may be effected through the steering mechanism; and
- C. linkage operatively connected between the boom and the bearing mount in a manner such that lateral displacement imparted to said boom serves to impart lateral displacement to said bearing mount, whereby the brush is caused laterally to be displaced relative to the center line of the machine as the roller supported end of the boom is caused to follow a preselected path along the surface of the highway.

33. The machine according to claim 6 further comprising an extended boom mounted at the leading portion of the machine and interconnected with the steering mechanism and adapted to be steered to follow a selected path.

34. The machine of claim 1 further comprises:

- A. a supporting frame pivotally connected at one end thereof to said mobile frame and depending therefrom;
- B. means connected with the supporting frame adapted to engage the given surfaces and support the supporting frame for displacement therealong; and
- C. means mounting said adhesive applicator and said button applicator on said supporting frame.

35. The machine of claim 6 further comprises:

- A. a supporting frame pivotally connected at one end thereof to the vehicle to depend therefrom;
- B. means connected with the supporting frame adapted to engage the surface of the highway and support the supporting frame for displacement therealong; and
- C. means connecting said adhesive applicator, button orienting means, button applicator, and pressure applicator to said supporting frame.

36. The machine according to claim 35 wherein the pressure applicator includes a pneumatic tire positioned at a preselected spacing above the surface of the highway, and bearing means supporting the tire adjacent the button applicator, whereby as the buttons are deposited in the globs of applied adhesive the pressure applicator is caused to engage the upper surfaces thereof.

37. The machine according to claim 36 wherein the bearing means are supported for fore-and-aft adjustment relative to said button applicator by means including screw-threaded blocks coupled with said supporting frame.

38. The machine according to claim 37 further comprising a

reciprocating actuator operatively coupled with the supporting frame and adapted to be actuated for rotating the supporting frame about said one end whereby the frame is caused to be elevated relative to said surface of the highway.

UNITED STATES PATENT OFFICE
CERTIFICATE OF CORRECTION

Patent No. 3,590,701 Dated July 6, 1971

Inventor(s) Terry K. Ten Broeck

It is certified that error appears in the above-identified patent and that said Letters Patent are hereby corrected as shown below:

Column 2, line 22, "divivider" should be ---divider--- and ---line---should be inserted after "divider".

Column 5, line 75, a period----- should be inserted after the word "buttons".

Column 8, line 66, the second "it" should be changed to ---is---.

Column 10, line 45, "FIGS. 10 an 11" should read ---FIGS. 10 and 11---.

Column 12, line 57, "17" should be changed to ---178---.

Column 13, line 15, "108" should be changed to ---208---.

Column 15, line 49, "V-belt" should be changed to ---V-belts---.

Column 16, line 10, "reciprocated;" should be deleted and ---286--- should be inserted after the word "beam".

line 26, "spring-biased" should be deleted and ---will---should be inserted in its place.

line 55, "rotate" should be changed to ---rotated---.

Column 18, line 64, "37" should be changed to ---372---.

line 69, "pine" should be changed to ---pin---.

Column 19, line 15, "AS" should be changed to ---As---.

Column 20, line 34, "be" should be changed to ---the---.

UNITED STATES PATENT OFFICE
CERTIFICATE OF CORRECTION

Patent No. 3,590,701 Dated July 6, 1971

Inventor(s) Terry K. Ten Broeck page - 2

It is certified that error appears in the above-identified patent and that said Letters Patent are hereby corrected as shown below:
Continued - Pg. 2

Column 20, line 68, "B1" and "G1" should be changed to
---B₁--- and ---G₁---.

Column 24, line 35, "foreces" should be changed to ---forces---.

Column 25, line 74, ---to--- should be inserted after "It is".

Column 28, line 4, "caste" should be changed to ---caster---.

line 24, "relived" should be changed to ---relieved---.

Column 29, line 38, "instance" should be changed to
---instances---.

Column 30, line 46, "or" should be changed to ---of---.

Column 32, line 2, "w" should be deleted at the end of the line.

line 19, "v-shaped" should be ---v-shaped---.

Column 33, line 60, "reciporated" should be ---reciprocated---.

line 64, "reciprocated;" in the second instance
should be deleted and ---and--- should be
inserted in its place.

line 68, "spirng" should be changed to ---spring---.

Column 34, line 54, "thereform" should be changed to
"therefrom---".

Signed and sealed this 11th day of January 1972.
